APPARATUS FOR STRETCHING METAL PLATE
Arthur Dean Smith, San Lorenzo, Calif., assignor to
Kaiser Aluminum & Chemical Corporation, Oakland,
Calif., a corporation of Delaware
Filed Dec. 11, 1962, Ser. No. 243,943
38 Claims. (Cl. 205—1)

This invention involves devices for stretching materials. Specifically, the invention involves an apparatus for stretching metal sheet or plate of considerable width, length and thickness to improve the physical properties thereof. This application is a continuation-in-part of my application Serial No. 673,032, filed July 19, 1957, entitled Apparatus and a continuation-in-part of my application Serial No. 796,566, filed March 2, 1959, entitled Apparatus, both now abandoned.

The beneficial results to be obtained from stretching of metal plate and sheet are known and there are a variety of types of stretching equipment available on the market for accomplishing this purpose. The known equipment, however, is limited in capacity and thus there are size limitations imposed on the workpiece that may be stretched. These limitations are present because of the fact that, as the workpiece size increases, the prior designs do not have the capacity size-wise to handle the article and further due to the fact that the physical design of the known equipment is not such that it may be adapted by a mere change in size to use where tremendous forces are developed such as are contemplated in the instant invention.

The present apparatus, to be herein described, is adapted to handle plate of a large size; for example, plate 60 feet long, 12 feet wide and having a thickness of six inches. The stretcher itself must be capable of producing a stretching capacity of over 30 million pounds.

To develop such capacity it is believed obvious that the apparatus must be so designed as to place each of its components under the most favorable stress conditions, i.e., to prevent as much as possible the introduction therein of all unnecessary twisting and/or shearing stress and combination of such stresses. Also means must be provided to protect these components from damage, if during stretching, a plate should break, a not unusual incident.

In addition, in order to avoid the necessity of utilizing a hydraulic actuation means involving tremendous conduits and unreasonable volumes of fluid, an apparatus had to be perfected which will accomplish the intended purpose with commercially available and reasonably-sized hydraulic components such as pumps, valves, conduits and the like.

Accordingly, a purpose of the instant invention is to provide a stretching apparatus capable of generating loads far above those developed by any known apparatus.

Another object of the invention is to produce a stretching apparatus which will develop tremendous capacity without the use of components so large as to present fabrication problems.

Still another object of the invention is to produce a novel hydraulically operated stretching apparatus in which available components may be used to generate the stretching capacity desired.

An additional object of the invention is to provide a novel open backed jaw mechanism for clamping a workpiece during stretching thereof wherein the jaws are protected against damage by breakage of the workpiece.

Still a further object of the invention is to produce a novel hydraulic manipulating and stretching system.

Another object of the invention is to produce a novel pilot-operated sequence valve which will enable proper actuation of the apparatus.

2

Still an additional object of the invention is to provide a novel method of assembling jaw or stretcher heads of large capacity.

A further object of the invention is to provide means in the stretching apparatus to protect the hydraulic system and operating parts thereof against damage due to accidental breakage of a workpiece.

An additional object of the invention is to provide a stretching apparatus in which maximum freedom or "floating" of the operating parts is accomplished.

Still a further object of the invention is to produce a stretching apparatus wherein the forces generated in the apparatus are made to approximate as nearly as possible linear and opposite vectors.

Another object of the invention is to provide means for coordinating the movement of opposite sides of the stretching heads.

These and other objects of the invention may be accomplished by providing a pair of clamping heads or assemblies, one "moveable" and one "fixed," interconnected by a pair of identical mechanisms along which the so-called "fixed" head may be adjusted and locked relative to the "moveable" head, these mechanisms including internal pilot-operated valve means for controlling the operation of a pair of manipulating cylinders and a pair of stretching cylinders. The head assemblies further include open backed jaw apparatus for clamping a workpiece and guide rollers for directing the ends of the workpiece into the jaws. A unique method of assembling the jaw mechanisms is also contemplated and suitable mechanisms are provided, including hydraulic components, to operate the jaws, stretcher mechanism, etc., these including safety devices to protect the expensive components against damage should a workpiece rupture during the stretching cycle.

The accomplishment of the objects mentioned and others inherent in the invention, though not specifically referred to herein, as well as the operation thereof will become apparent when consideration is given to the following detailed description of the invention when reviewed in conjunction with the appended drawings, wherein

FIGURE 1 is a side elevational view of the apparatus comprising the invention, certain moveable parts being shown in dotted as well as full line, certain parts being broken;

FIGURE 2 is a top plan view of the apparatus shown in FIGURE 1, again with parts broken away for clarity;

FIGURE 3 is an enlarged rear elevational view partly in section of one of the gripping head assemblies, taken along the line 3—3 of FIGURE 2;

FIGURE 4 is an enlarged front elevation, partly in section of the same gripping head assembly, taken along the line 4—4 of FIGURE 1;

FIGURE 5 is an enlarged vertical sectional view of the head assembly shown in FIGURES 3 and 4 and taken along the line 5—5 of FIGURE 4;

FIGURE 6 is an enlarged vertical section showing details of a head assembly and its attachment to the tube-like means or tubular assemblies shown in FIGURE 2, and taken along the line 6—6 shown therein;

FIGURE 7 is an enlarged vertical sectional view taken along the line 7—7 of FIGURE 2 and showing details of stretcher and manipulating cylinders;

FIGURE 8 is an enlarged sectional view of the sequence control valve used to control the actions of the manipulating and stretching cylinders, its location being indicated by dotted lines in FIGURE 2;

FIGURE 9 is a sectional view, enlarged, of the snubber cylinder construction, their location being apparent in FIGURE 2;

FIGURE 10 is a sectional view through one of the safety pressure relief valves incorporated in the manipulating rod piston as indicated in FIGURE 8;

FIGURE 11 is a sectional view taken along the lines 11—11 of FIGURE 10;

FIGURE 12 is a sectional view taken along the line 12—12 of FIGURE 10;

FIGURE 13 is a schematic diagram of the external hydraulic circuit and the components utilized therein, this system being used in conjunction with the sequence valve shown in FIGURE 8 and the manipulating and stretching cylinder assemblies shown in FIGURES 1, 2, 7 and 8;

FIGURE 14 is a schematic view of a hydraulic system utilized to control the plate guiding rolls and jaw assemblies shown in FIGURES 3, 4 and 5;

FIGURE 15 is a schematic view of a differential control mechanism which may be used to equalize movements of both sides of the apparatus;

FIGURE 16 is a view of a novel clamping ring which may be used in assembling the head assemblies shown in detail in FIGURES 3, 4, 5, etc.;

FIGURE 17 is a top plan view of another embodiment of the stretching apparatus defining the invention;

FIGURE 18 is a side elevational view of the apparatus shown in FIGURE 17;

FIGURE 19 is an enlarged broken partial side and sectional view of the apparatus shown in FIGURE 17 and discloses one of the workpiece gripping heads as defined hereinafter and details of a tubular assembly and hydraulic motors which actuate the said apparatus;

FIGURE 20 is an enlarged partial side view, partly in section, of the opposite end of the apparatus of FIGURE 17 and, if viewed with FIGURE 19, the two figures form a complete side and partially sectional view of the said apparatus;

FIGURE 21 is a front elevational view of a workpiece gripping head taken along the line 21—21 of FIGURE 17 with certain parts being shown in section;

FIGURE 22 is a sectional view of the gripping head taken along the line 22—22 of FIGURE 21 and shows some details of the workpiece gripping jaw assemblies;

FIGURE 23 is a rear elevational view of the gripping head shown in FIGURE 21 with parts thereof being shown in section;

FIGURE 24 is an enlarged detail view of the jaw-operating mechanism and discloses that portion of the internal details of the jaw-operating mechanism not shown in FIGURE 22;

FIGURE 25 is an enlarged view of a portion of one side of a gripping head for the apparatus of FIGURE 17 and discloses the manner in which the gripping heads may be releasably engaged by the tubular assemblies;

FIGURE 26 is an enlarged sectional view through one of the tubular assembly shock absorbers shown in FIGURES 17 and 18;

FIGURE 27 is an enlarged view of certain details of a workpiece lifting and guiding assembly which though not shown in FIGURES 21 and 22 for the purposes of clarity nonetheless may be advantageously incorporated in the apparatus of FIGURE 17;

FIGURE 28 is an enlarged side sectional view taken through the novel sequence control valve utilized in the apparatus of FIGURE 17, the location of which is generally indicated by dotted line in FIGURE 19 and which will be further seen in dotted line outline in FIGURE 29;

FIGURE 29 is a schematic hydraulic circuitry diagram showing the main control system used for actuating the device of FIGURE 17 in all phases of its operation;

FIGURE 30 is a schematic view of a secondary system used with the apparatus of FIGURE 17 to cause positioning and gripping of a workpiece between the jaws as will be subsequently apparent; and

FIGURE 31 is a schematic view of an equalizer system which in practice is used in conjunction with the hydraulic system shown in FIGURE 29 as indicated therein.

Referring now in particular to FIGURES 1 and 2 the overall assembly of a plate stretching apparatus shown therein and comprising one embodiment of the instant invention may be clearly understood. Generally, the apparatus will be disposed in a pit-like area 1, having side walls 2 and end walls 3 and 3'. Closely adjacent the pit area 1 there is provided an operator's control station 4 (FIGURE 2). It will be understood that the manual operating controls for the apparatus will be located at this station 4 and that, in the description to follow, it will be apparent that such operator-operated controls as may be mentioned are so located.

The pit floor 5 is level and is generally rectangular, being of such area as to readily accommodate the elements comprising the stretching apparatus as well as to permit movements of both these elements and the workpiece within the necessary limits of the apparatus. The floor area is also provided with spaced pairs of rails 6 and 7. These rails are parallel and extend longitudinally of and are symmetrical with respect to the center line of the longer dimension of the pit area.

In the description of the apparatus which follows hereinafter, reference will be made to a so-called "fixed" and a so-called "moveable" stretcher head. This nomenclature is applied to distinguish the head mechanisms 100 and 200, one from the other since, though having many common features, these mechanisms are not identical in all particulars. Therefore, by "fixed" head is meant the head assembly 100 which does not move during the actual manipulating and stretching cycles to be described. Similarly, reference to the "moveable" head is directed to the head assembly 200 which is that assembly that actually moves during these manipulating cycles.

Having defined the terms to be used and referring to FIGURE 1, it may be seen that the apparatus includes a pair of somewhat similar head elements 100 and 200 provided with suitable jaw and hold-down mechanisms, to be described, which are adapted to engage and clamp the ends of a workpiece and to hold these ends during the stretching thereof. The head mechanism 100 is connected to the head mechanism 200 through a pair of identical tube-like means or tubular assemblies 300, 300', a pair of stretching cylinder assemblies 400, 400', a pair of jack screw mechanisms 600, 600' and a pair of manipulating rods 302, 302', the functions of all of which will become apparent as the description of the apparatus proceeds. Each of the respective head assemblies 100 and 200 is mounted on pairs of wheeled dolly-like supports 101 and 201, respectively. The wheels of the dolly-like supports in turn ride upon and are guided by the symmetrically arranged, spaced pairs of rails 6 and 7 provided on the pit floor 5.

The head assembly 100, as has been stated, is provided with jack screw mechanisms 600, 600'. These mechanisms are in turn engaged with the screw threaded outer circumferences of the tubular assemblies 300, 300' and, when operated as will be described, serve to move the head assembly 100 along the tubular assemblies toward and away from head assembly 200. The head assembly 100, however, is moved solely to vary the span or distance between it and head assembly 200 to accommodate various lengths of workpieces. Since this head assembly 100 is not moved during the working or stretching cycle of the apparatus, this head is the so-called "fixed" head assembly.

The head assembly 200 is connected to the tubular assemblies 300, 300' through the medium of stretching cylinder assemblies 400, 400' and manipulating rods 302, 302'. This latter head assembly also rides on its dolly-like supports 201, the wheels of which also ride upon the mentioned pairs of parallel rails 6 and 7. Since this head assembly 200 is that which moves, due to the action of stretching cylinder assemblies 400, 400' during the stretching cycles, it comprises the so-called "moveable" head assembly.

The ends of the tubular assemblies 300, 300' most closely adjacent the moveable head assembly 200 are supported on a transversely extending floating support assembly 500. This support assembly 500, as will be described, is moveable transversely of its width, i.e., in a direction generally axially of the length of the stretching apparatus, and may also comprise a housing 520 for the various hydraulic components, such as valves, pumps, etc., which are utilized to operate the apparatus. The other ends of tubular assemblies 300, 300' are also mounted on floating support assemblies 550, 550' as will be apparent as the description of the apparatus proceeds. In addition, the "fixed head" ends of the tubular assemblies 300, 300' are connected to the pit wall 3 by a pair of shock absorbing and "squaring" devices 360, 360'. These devices are suitably mounted in the pit wall and serve not only to keep the stretcher tubular assemblies 300, 300' in end-to-end alignment, but also as shock absorbers which receive and absorb the tremendous shock loads which will occur should a workpiece rupture or fail during a manipulating cycle of the stretching apparatus.

The overall arrangement of components having been described, detailed consideration will now be given to the elements which make up the specific components of the apparatus. In this connection and in order to avoid confusion, it will be noted that where two items are identical, only one such item will be described. It will be understood, however, that such items as may be so described, will be operated simultaneously and act in identical fashion. A prime example of such identically acting components is stretcher tubular assemblies 300, 300', wherein a description of one will serve adequately as a description of both.

Referring now to the stretcher head mechanisms, and in particular to FIGURES 3, 4 and 5, the arrangement of parts which are common to both head assemblies 100, 200 will be described. For the purposes of illustration, the so-called "fixed" head assembly 100 has been selected and will be described in detail. Generally, the head 100 is comprised of a pair of upper and lower identical anchor beams 102, 102' in the form of large castings. As is clearly shown in FIGURE 5, these anchor beams are held in assembled relation by a pair of generally oval-shaped strap members 104, 104', the ends of the anchor beams 102, 102' being shaped to fit within the oval straps 104, 104'.

Referring in particular to FIGURE 5, it may be seen that between the straps 104, 104' the opposing anchor beams have a configuration such that they define what generally may be defined as a slot S extending from front to rear, through which a workpiece W, shown only in FIGURE 5, may pass.

The slot is, of course, horizontally disposed and the maximum dimension thereof, i.e., the thickness of the workpiece W that may be passed therethrough, is determined by the vertical spacing between planar faces 106, 106' provided on the anchor beams 102 and 102'. As seen in FIGURE 5, the planar faces terminate rearwardly at a line defined by their intersection with a pair of diverging planar faces 108, 108', also provided on the opposing faces of the anchor beams 102, 102'. The leading edge of the planar faces 106, 106' terminates at a line defined by their intersection with vertical walls 110, 110', which in turn terminate in horizontal portions 112, 112' which define ledges or shoulders in the inner or working face of the anchor beams 102, 102'.

Considering now the diverging faces 108, 108', it may be seen that each of these planar faces is provided with a jaw-guiding member 114, 114'. These jaw guide members are comprised of hardened steel, or the like, having properties such as to resist wear due to friction as well as to resist very high loads in compression. Each of the guide members 114, 114' is provided with a plurality of guide ribs 116, 116'.

Between each pair of guide

ribs 116, 116' there is fit a plurality of individual gripping elements or wedges 118 or 118', as will be apparent, thus the number of guide ribs 116, 116' is a function of the number of gripping elements or wedges 118, 118' which are used. In the drawings, there are shown ten gripping elements or wedges 118, 118' and thus there would be provided eleven such guide ribs 116, 116' on each of the upper and lower members 114, 114'. It will be appreciated that these gripping elements or wedges 118, 118', particularly those provided on the upper anchor beam 102, must be held in place to prevent their falling from between the guide ribs 116, 116'. A simple and rather conventional means for locking the wedges in place is effected by providing each side face of each wedge 118, 118' with a slot or recess 119, 119'. Thus, between each two elements 118, 118' there is defined a keyway formed by the oppositely facing slots 119, 119' into which may be inserted an elongated key 120, 120', as the case may be, each of the keys 120, 120' being fixed, preferably by counter-sunk bolts, to the top of each of the guide ribs 116, 116'. Thus, it may be seen that each of the jaw elements or wedges 118, 118' is fixed to the hardened guide plates 114, 114' in such a manner that they may be moved forwardly and rearwardly (as shown in FIGURE 5) on the diverging surfaces 108, 108'.

As is also clearly shown in FIGURE 5, the jaw or gripping elements 118, 118' are in the form of wedges. The actual workpiece gripping surfaces 122, 122' between any two pairs of upper and lower gripping elements 118, 118' are parallel and because the angle at which each of the diverging surfaces 108, 108' is equal, these gripping surfaces will always remain parallel regardless of the position at which these gripping elements may be along the guide plates 114, 114'. The gripping surfaces 122, 122' may preferably be provided with hardened inserts 124, 124' having serrated faces which engage the workpiece W and thus since these inserts may be readily removable the useful life of the gripping elements may be prolonged indefinitely.

Referring now to FIGURE 3 and considering this drawing in conjunction with FIGURE 5, the details of the gripping wedge actuating mechanism will now be described in detail.

On the rear of the anchor beams 102, 102' are mounted, as by bolting, a series of similar, laterally spaced upper and lower brackets 126, 126', respectively. These brackets 126, 126' are so arranged that they are disposed medially between each adjacent wedge or gripping element of the plurality of such elements 118, 118'. As seen in FIGURE 5, these brackets 126, 126' are generally L-shaped in elevation with their longer legs terminating in trunnion journal blocks 128, 128' and backed against the upper and lower anchor beams 102, 102', respectively, and their shorter legs in parallel relation and terminating in shaft journals 130, 130'. Within the journals 130, 130' and extending horizontally across the rear of each of the anchor beams 102, 102' there are disposed a pair of parallel rotatable upper and lower vertically coplanar shafts 132, 132', respectively. The opposite ends of these shafts 132, 132' are connected together through the medium of pairs of identical segmental spur gears 134, 134', 135, 135', respectively. Since each of these segmental gears is keyed to the respective shafts 132, 132' upon which they are mounted, it is obvious that shafts 132, 132' must move clockwise and counterclockwise simultaneously and at the same rate. Also fixed to the parallel, interconnected shafts 132, 132' are a plurality of identical upper and lower bell cranks 138, 138', respectively. These bell cranks are disposed on shafts 132, 132' such that each lies direct behind a gripping wedge 118 or 118', respectively, and each of the bell cranks is keyed to its respective upper shaft 132 or lower shaft 132' by a conventional key 140, 140', respectively. Thus, since upper and lower shafts 132, 132' move simultaneously, each of the identical upper and lower bell cranks 138, 138' will move simul-

taneously. The ends 142, 142' of each of the bell cranks, in case of the upper bell cranks 138 the lower end, and in the case of the lower bell cranks 138' the upper end, are connected to long slender connecting rods 144, 144', respectively, each of which in turn is connected to each of the gripping elements 118, 118', respectively, by suitable pins 147, 147' provided in suitable receptacles or cylinders 148c, 148d. Thus, rocking movement of the respective bell cranks will cause sliding movement either inwardly or outwardly (opening or closing) of the gripping elements or wedges 118, 118' to which they are connected by the long slender column-like connecting rods 144, 144'.

With respect to the rods 144, 144', it is to be noted that in the description above they have been referred to as long slender rods as, in fact, they are. Each of the rods 144 or 144' is so designed as to act in a manner similar to an unstable column. In other words, their strength in tension is sufficient to pull the gripping elements free of a workpiece after completion of an operation of the apparatus thereon. Each is also of a design strength such as to be able to easily push the gripping elements 118, 118' into engagement with a workpiece. However, their strength in compression is such that if overloaded they will buckle easily. Preferably, not only will these rods buckle, but also in a preferred arrangement each is made of resilient material, such as spring steel, in order that once the excessive load is removed they may return to their normal position.

The reason for the described arrangement will not be delved into in great detail at this point, but it can be said that the purpose, a safety factor, will become apparent when the operating description of the apparatus is considered.

Referring again to bell cranks 138, 138', it may be seen from an inspection of FIGURE 5 that the opposite ends thereof to those previously described, i.e., the lower ends of cranks 138' and the upper ends of cranks 138, are connected to the piston rods 146, 146' of a plurality of hydro-pneumatic cylinders 148, 148'. Each of the cylinders 148, 148' is trunnioned in the trunnion or journal blocks 128, 128', respectively, and thus may rock about the axis of the trunnions 150, 150'. This arrangement is necessary, of course, because the ends of the bell cranks 138, 138' do not move linearly but rather in an arcuate path.

It suffices to say, at present, that as piston rods 146, 146' move out of their respective cylinders 148, 148' under the influence of suitable pneumatic pressure means, the gripping elements are caused to move together along the diverging surfaces 108, 108' to grip the workpiece W. Similarly, as the piston rods 146, 146' are retracted within the cylinders 148, 148' by suitable hydraulic means the gripping wedges 118, 118' are pulled back along the diverging surfaces and thus release the workpiece.

It will, of course, be noted that the cylinders 148, 148' are referred to as hydro-pneumatic, i.e., operated in one direction by hydraulic pressure, and in the other direction by air or gas pressure. The reasons for and manner in which the cylinders are so actuated will be deferred until such time as the operation of the actuating apparatus is discussed in detail.

As was mentioned, the inner faces of the anchor beams, i.e., the faces directed toward the workpiece W, are provided with a similar pair of parallel upper and lower shoulders 112, 112', respectively. Considering now FIGURE 4 in conjunction with FIGURE 5, their purpose will become readily apparent. Dependently attached to the upper shoulder 112 are a plurality of individual hydraulically actuated cylinders 152. These cylinders are fixed to the shoulder 112 by any suitable means preferably as by bolting or the like through a series of mounting pads 153. The lower ends of the cylinders rest against and are fixed to a guide plate 156 provided on vertical wall 110 by a common bracket 157. From the lower end of the cylinders 152 project the usual telescopic piston rods

154. The lower end of each piston rod 154 has attached thereto as by screw threads and nuts or the like, a yoke assembly comprised of a horizontal plate 158 having depending ears 160, between which on suitable journals or trunnions is fixed a roller 162. Thus, as seen in FIGURE 4, the upper leading or workpiece entering edge of the slot S is defined by a plurality of generally coaxial, vertically moveable, hydraulically actuated rollers 162. In FIGURE 5, it may be seen that each of the plates 158 has its rear edge in sliding contact with the face plate 156. Thus, the plates 158 prevent twisting of the rollers 162 about the axis of the piston rods 154 and serve further to reinforce the piston rods 154 against bending, when, for example, workpiece W is moved into the slot S. Since these rollers 162 are moved away from the workpiece W after stretching thereof and during its removal it is only necessary to reinforce the piston rods 154 in one direction only.

The lower anchor beam casting 102' is also provided with a roller assembly 170 which rests upon and is fixed to the shoulder or ledge 112'. This assembly differs considerably in operation and structure from the top rollers 162, and hence warrants detailed treatment.

Again, referring to FIGURES 4 and 5 in particular, it may be seen that bolted or otherwise fixed to the shoulder or shelf 112' is a transversely elongated base plate 172. Paralleling the central longitudinal axis of this base plate 172 in spaced coaxial relation thereon, there is provided a pair of ribs 174, 174'. In slidable engagement with the base plate 172 and having slots registered on the ribs 174, 174' are a pair of solid block members 176, 176' having sloping upper surfaces 178, 178' such that these blocks define wedges. Obviously, the blocks 176, 176' are slidable toward and away from each other and as so disposed that the sloping surfaces 178, 178' face toward each other. In order to move the wedges toward and away from each other and to obtain simultaneous equal and opposite movement of each of the blocks 176, 176' each block is provided with a threaded aperture, each of which in turn receives the opposite ends of a driven shaft 179. The ends of the shaft 179 are threaded and conventionally the threads are of opposite pitch. In other words, as viewed in FIGURE 4, the right-hand end of shaft 179 is provided with a left-hand thread while the left-hand end is provided with a right-hand thread. The shaft 179 is connected to a reversible electric motor 180 by the usual pulley and belt drive 182 as is conventional. Thus, as the motor drives shaft 179 in one direction, the blocks 176, 176' will be moved simultaneously and equally toward each other. If rotated in the opposite direction, the shaft 178 will cause similar movement of the wedges 176, 176' away from each other.

Overlying the wedge and drive mechanism described immediately above, is an elongated, transversely extending, channel-shaped carrier beam 184. Preferably, this carrier channel is so disposed as to open downwardly. Disposed interiorly within the channel in the pocket defined by the web and flanges of the carrier beam 184 are a pair of additional wedge-shaped blocks 186, 186'. These blocks 186, 186' are provided with sloping bottom faces 188, 188'. These faces rest on the sloping top faces 178, 178' of the moveable blocks 176, 176' and, obviously, as the latter are moved toward and away from each other the carrier will be moved upwardly and downwardly.

Mounted upon the upper face of the carrier are a plurality of rollers 190 suitably journaled in suitable apertured brackets. These rollers are arranged in coaxial coterminous relation and, of course, will be carried upwardly and downwardly in response to similar movement of the carrier beam. It might be well to note that the ends of the carrier beam 184 are provided with vertically disposed plates 192, 192' which ride in vertical slots (not shown) provided in the faces of the anchor beams 102, 102' to assure that movement thereof will be truly vertical and further to maintain the carrier in proper position.

Because of the fact that the friction between the sloping surfaces 178, 178' and 188, 188', respectively, is considerable, and further, due to the fact that the friction between the threaded shaft 178 and the blocks 176, 176' is considerable, it will be apparent that once the rollers 190 are set at a selected vertical position they will remain fixed so long as the motor 180 is not energized. Preferably, the rollers 190 are always adjusted such that the upper surface defined by their peripheral surfaces is always disposed below an imaginary planar surface passing through the slot S exactly one-half of the dimensional thickness of the plate or workpiece W being stretched. The purpose of this arrangement is to assure that as the cylinders 152 are actuated to bring hold-down rolls 162 in contact with the workpiece W the workpiece will be aligned as nearly as possible with a plan extending medially through the slot S. Thus, the wedge-like gripping members 118, 118' will grip the top and bottom surfaces of the workpiece W at approximately the same distance from its end and no off-center loading is created in the workpiece by these latter members.

Referring now briefly to FIGURES 1 and 2, it will become apparent that the above description has been directed to the common structure incorporated in the two head assemblies 100 and 200.

In FIGURES 1 and 2 it will be noted that reference numerals of a 200 series are shown in connection with a few of the visible elements of head assembly 200. These numerals indicate the same components in head assembly 200 as do their counterpart reference numerals in the so-called 100 series, and have been so used to assure that no confusion will occur by reason of the fact that only one of the head assemblies, namely, "fixed" head assembly 100, has been described in detail.

As has been indicated, the jaw-operating cylinders 148, 148' are hydro-pneumatically actuated while the hold-down roll cylinders 152 are hydraulically actuated. A desirable hydro-pneumatic system for actuating the clamping cylinders 148, 148', as well as hold-down cylinders 152, is shown schematically in FIGURE 14.

The gripping members 118, 118' are preferably so operated as to be pneumatically closed under the influence of a constant pressure exerted on the hydro-pneumatic operating cylinders 148, 148'. It suffices to say presently that such an arrangement permits the incorporation of features wherein the workpiece gripping assemblies are protected from damage due to accidental failure or rupture of a workpiece W. Also, since the jaws are constantly being urged to a closed position, the operating circuit must and does include a safety interlock means to prevent accidental closure, particularly at such times as may result in injury to persons engaged in repair or maintenance of the apparatus. Also, since the hydraulic system preferably also operates the hold-down rolls 162, it is most desirable that these elements also be locked in a withdrawn position such that their weight will not cause their accidental lowering. The hydro-pneumatic system incorporates such features and safety interlocks as will be apparent from the detailed description to follow in conjunction with FIGURE 14 of the drawings.

Referring briefly to the jaw-operating cylinders (only one cylinder 148 being shown in the diagram for simplicity) it may be seen that each of these cylinders 148 is a double acting cylinder having a single inlet-outlet line 111 connected to the rod end. The rod end of the cylinder is supplied with hydraulic fluid from the system to be described, while the head end thereof is supplied with an inert gas, such as nitrogen, from a pressure accumulator 113. Thus, the pressure being exerted by the inert gas from the accumulator 113 on the piston 115 in the cylinder tends to urge this piston to the left as shown in the drawings. Since the piston rod 117 is connected to bell crank 138, it is obvious that the bell crank will be rotated in a counterclockwise direction. The bell crank 138, of course,

is connected to the gripping elements previously described by means of the rods 146.

It will be apparent that the counterclockwise rotation produced on the bell crank 138 will urge the gripping member 118 to its closed position. Thus, the pressurized gas acting on the head end of cylinder 148 serves to close the gripping members 118 clamping the workpiece in place. The hydraulic system then must oppose this pressure to open the members 118, 118', as shown in FIGURE 5, to release the workpiece.

Also provided in the hydraulic circuit schematically shown in FIGURE 14 is a single representation of the hydraulically operated cylinder 152 which actuates the top bending or guide rolls 162. This cylinder is provided with a piston 119 having a rod 154 connected to the pressing or guide roll 162, inlet-outlet conduits 136 and 137 may be attached to both head and rod end of this cylinder assembly.

Referring now to the various components making up the system, it may be seen that the operating pressure for the hydraulic system is obtained from a single fixed displacement pump P driven by an electric motor M. The intake side of the pump is connected to a suitable large capacity tank T through a suitable filter or strainer F.

The output side of the pump P is connected to a conduit 121 which in turn is connected to a three-position, open-center, solenoid-operated valve 123. This valve 123 is provided with four ports 127, 129, 131 and 133. These ports may be interconnected in various ways by movement of a usual ported valve spool in response to energization of the left- and right-hand solenoids L and R. In the centered position of the valve spool as shown in the drawing, port 127 is thus in communications with conduit 121, port 129 with conduit 133', port 131 with conduit 136 and port 133 with conduit 137. Of the mentioned conduits, conduit 136 is in communication with the rod end of the hold-down roll cylinder 152, conduit 137 with the head end of this cylinder, while conduit 133 is in communication with a second, solenoid-operated valve 145.

It will be noted further that conduit 121 leading from the pump P is also connected to a maximum limit pressure relief valve 125 which has its outlet or exhaust side connected to the tank T. The function of this valve 125 is to maintain the pressure in the system in accordance with the output of the pump P and to open or dump into the tank T should for any reason the pressure necessary to operate the system exceed the maximum desired p.s.i. Also connected to conduit 121 is a visual pressure gage 127' which indicates to the operator that the system is properly pressurized.

It may be seen that valve 145 is of the so-called three-position, open-center, solenoid-operated type also. The spool of this valve is actuated by right- and left-hand solenoids L and R so as to interconnect these various ports in the manner as will be apparent. Thus, this valve 145 also is provided with four ports 141, 143, 147 and 149. In centered position of the spool, however, port 141 is in communication with conduit 133', port 149 with a pilot line 151, port 143 to the tank T and port 147 to a conduit 157. The pilot line 151 is connected to a pilot-operated check valve 160' having its output side connected to the rod or hydraulic side of the jaw-operating cylinder 148. The conduit 157 is connected to the input side of the pilot-operated check 160', the operation of which will become apparent.

In describing the operation of the system, let it be assumed that, as schematically shown in FIGURE 14, all of the components are in normal "rest" condition and that both the jaws 118, 118' and hold-down rolls 162 are in retracted position. The pump P then passes fluid through conduit 121 to the centered, solenoid-operated valve 123, and is bypassed by this valve, entering port 127 and exhausting through port 129 to the conduit 133'. Conduit 133' directs fluid to the valve 145 which is in centered position with ports 141, 143, 147 and 149 in communica-

tion. Thus, fluid is admitted to and may pass through the pilot line 151 from port 149. The fluid in the pilot line 151, however, does not operate valve 160' because of the bypass connection between ports 141 and 143 in valve 145. Thus, while the pilot line is pressurized, the fluid will pass from port 141 to port 143 and return to the tank T.

Because of the fact that valve 123 is blocked, it will be apparent that conduits 136 and 137 are blocked and that the hold-down cylinder 152 cannot move. Similarly, since the pilot-operated check valve 160' is seated, there is a hydraulic lock on the rod end of the gripping cylinder 148 and thus the gas pressure on the head end cannot move the piston 115. The primary purpose of the check valve 160' is to assure that the gripping members 118, 118' remain open and do not "drift" closed as would be the case were reliance had solely on the blocking of valve 145. This is true because all such valves are subject to some internal leakage and thus the blocked fluid in the jaw-operating cylinder 148 would gradually leak out allowing the piston 115 to move to the left closing the members 118, 118'.

Assuming now that a workpiece W has been positioned for loading in the stretching apparatus, the operator by suitable means (a button control panel at station 4) energizes the left-hand solenoid L of valve 123. The spool of the valve will move to the left, thus interconnecting ports 127 and 133, also ports 129 and 131. Thus, fluid will enter the head end of cylinder 152 and exhaust from the rod end thereof passing through the valve 123, conduit 133', valve 145, through port 141 and out of port 143 to the tank T. When the hold-down rolls engage the workpiece W, the valve 123 is again de-energized. Thus, the end of the plate is flattened and may pass between the open gripping elements 118, 118'.

The operator will then energize, by remote control, the right-hand solenoid R of valve 145. This moves the valve spool so as to place pressure on pilot line 151 and also places ports 147 and 143 in communication. The pilot will open check valve 160' allowing fluid to exhaust from the rod end of the jaw cylinder 148, through line 157, ports 147 and 143 to tank T. The gas pressure from the accumulator 113 will then move the piston 115 to the left, thus moving the gripping wedges 118. Similarly, wedges 118' will be so moved. The check valve 160' is held open during the stretching cycle in order that any movement of the gripping members 118 in biting into the workpiece W will be able to move the piston 115.

The stretching of the workpiece having been completed, as will be described, the operator energizes the left-hand solenoid L of valve 145, the valve spool placing in communication port 141 with port 147 and also port 149 with port 143. The pilot line is thus exhausting to tank T and the check valve 160' may close. However, pressure on conduit 157 will keep the valve open as fluid passes into the rod end of the gripping cylinder 148 pushing piston 115 against the inert gas which it overcomes forcing the gas to recharge the pneumatic accumulator. When the jaws are completely retracted, valve 145 is centered and again the check valve 160' closes, locking the gripping wedges 118 open.

When the workpiece is ready for removal, the operator energizes the right-hand solenoid R of valve 123. This shifts the spool to put ports 127 and 131, as well as ports 129 and 133, in communication. Thus, the rod end of the hold-down cylinder 152 is pressurized through conduit 136 while the head end exhausts through conduits 137, 133', valve 145 back to the tank T. Thus, piston 119 will be forced upwardly and will act to retract the hold-down rolls 162. When the retraction of hold-down rolls 162 is complete, the valve 123 is returned to center by de-energization of solenoid R and again the cylinder 152 is blocked with the whole system at rest.

The reason for the use of a hydro-pneumatic jaw cylinder 148 is as follows: If a workpiece should break, the tremendous energy released tends to cause gripping mem-

5

bers 118 to fly open. Obviously, since the gas on the head end of this cylinder 148 is compressible, it will be compressed with piston 115 moving to the right. As it does, a suction is created on the hydraulic or rod side thereof which causes unseating of check valve 160 and entry of fluid therein through conduit 111. The cylinder acts then as a shock absorber and, as such, much of the energy will be dissipated as heat in compressing the gas. Also, as has been explained, the links 146 may collapse in the event the shock is so great as to exceed the ability of the gas to absorb the energy.

Thus, there is shown in FIGURE 14 a circuit which will operate the hold-down and clamping cylinders and which includes safety features acting to prevent damage to the gripping mechanism described. It will be appreciated that a similar circuit is used to actuate the gripping members and hold-down rolls on the head assembly 200.

By referring to the drawings, it may be seen that terminating with the above description is any similarity between the respective assemblies 100 and 200 and that accordingly the manner in which each is connected to the tube-like assemblies 300, 300' must be described in detail.

Accordingly, specific attention is now directed to FIGURE 6 along with FIGURES 1 through 4, inclusive. Again, since the means for connecting the head assembly 100 to the assemblies 300, 300' are identical, a description of one side should suffice as a description of both, primed numerals being used to indicate common parts.

As shown in FIGURES 1, 2, 3 and 4, the so-called "fixed" head assembly is fixed to a pair of externally threaded stretched assemblies 300, 300' by means of screw jack mechanisms 600, 600'. To effect the moveable connections, the head assembly 100 is provided on either lateral end with large ear-like members 602, 602'. These members extend outwardly beyond the area embraced within the spaced strap members 104, 104' and may be formed as upper and lower half castings integral with the upper and lower anchor beams 102, 102' or may be made in the form of integral cast units which are fixed to the properly assembled castings 102, 102'. From an inspection of FIGURES 3, 4 and 6, it will be seen that these ear-like members 602, 602' overlie the spaced pairs of rails 6 and 7 and also overlie the dollies 101. Accordingly, the bottom portions of the ear-like members are so formed as to include suitably configured portions 603, 603' which rest upon the top surfaces of the dollies 101.

While it is not believed necessary to delve into the construction details of the individual dollies 101 and 201 in great detail at this point, it will be noted that, as shown in FIGURE 7, the construction details of both the dollies and mode of connection to the respective heads is such that the heads 100, 200 are in a sense "floatingly" supported thereon, as will be described.

As is clearly evident in FIGURE 6, each of the projecting ear-like castings 602, 602' is provided with a large diameter smooth-walled cylindrical aperture 604, 604'. These apertures are of such a diameter as to permit the threaded assemblies 300, 300' to pass therethrough, as is clearly shown. Thus, the so-called "fixed" head assembly 100 is bracketed between the spaced parallel tubular assemblies 300, 300' and is readily moveable along the length of these columns riding on the rails 6 and 7 through the medium of the dollies 101. Because of the massiveness of the head assembly 100, it becomes readily apparent that some means must be provided to move the assembly, when necessary, along the tubular assemblies 300, 300', while at the same time means must be provided to lock the head assembly in an immobile position during a stretching cycle. Preferably, a single means for effecting both functions is used. An expeditious arrangement for accomplishing the desired results is shown. As seen in FIGURE 6, that face of the ear-like casting which is disposed toward the "moveable head" is provided with an annular recess into which is fitted an annular bushing 606. The inner circumferential edge of the bushing is

50

60

65

70

75

defined by a sloping wall 608 which forms a cone-shaped bearing surface.

Surrounding the threaded assembly 300 and being in threaded engagement therewith is an annular collar 610. This collar, of course, is provided with internal threads which engage the outer threads on the tubular assembly 300. Thus, it may be seen that as the collar is rotated in one direction or the other, it will act as a nut and will be caused to travel in one direction or the other along the threaded length of assembly 300. It will be noted that the outer peripheral surface of the collar 610 is comprised of two distinctly configured surface portions 612 and 614. These surface portions comprise a cone-shaped bearing surface 614 and a peripheral toothed portion 612, in which the peripheral toothed outer portion defines a spur gear, while the cone-shaped portion 614 defines a bearing surface adapted to bear against and be rotatable with respect to the bearing surface 608 provided on the annular bushing 606. The opposite side or face of the collar 610 terminates in an annular wall 616.

Surrounding the collar 610 is a generally hat-shaped housing member 620. This housing member is fixed to the apertured ear-like casting 602 by bolts 618. As may be clearly seen in FIGURES 4 and 6, this housing is also generally annular in form, and has a central aperture through which the assembly 300 may pass. The housing member is further provided with a peripheral flange 622 through which the bolts 618 or equivalent fastening means are passed to fix the housing 620 in proper aligned position on the ear-like member 602. This housing 620 thus serves a dual function; first of all, it is fixed on the head assembly in such a manner as to bear against the annular face 616 of the traveling collar 610 and, secondly, it is provided with an outwardly projecting trunnion member 624 in which is journaled a shaft 626 provided with a pinion 628. This latter pinion 628 is meshed with the toothed portion 612 of the annular collar 610.

It is believed apparent from the disclosed arrangement that as the collar 610 is rotated, not only will it rotate on the assembly 300, but, because of its bearing engagement with both housing 620 and annular bushing 606 it will carry the "fixed" head assembly with it as it traverses the assembly 300 in either direction. Thus, the mechanism accomplishes one of its previously indicated purposes, namely, as a means to enable movement of the "fixed" head assembly 100 along the tube-like assemblies 300, 300'. Secondly, because of the shallow pitch of the threads on assembly 300, the collar 610 will have little, if any, tendency to rotate even when the "fixed" head is under load, and thus it serves to lock the head assembly 100 to the assembly 300. It will, of course, be appreciated that while only one side connection of fixed head assembly 100 to the assembly 300 is described that a similar arrangement is provided on the opposite side of head assembly 100 which is connected to assembly 300' through the medium of jackscrew mechanism 600'. Thus, where both sides are shown, prime numerals are utilized to designate like parts on this opposite side.

It will be appreciated that considerable effort is necessary to rotate the collars 610, 610'. According, a common drive means is provided on the head assembly 100 for turning the collars 610, 610' and assuring proper movement of the head assembly along the tube-like assemblies 300, 300'. Referring now, in particular, to FIGURES 3 and 6, it may be seen that such a means is shown in detail. As previously indicated, the housings 620, 620' are provided with trunnions 624, 624' in which are journaled shafts 626, 626'. These shafts in turn are keyed to and carry a pair of pinions 628, 628', one of each being in engagement with the respective toothed portions 612, 612' of the collars 610, 610'. The shafts, as may be clearly seen from an inspection of the drawings, are disposed above and are parallel to the tube-like assemblies 300, 300' and each passes through the ear-

like members 602, 602', respectively, to a pair of gear boxes 630, 630'. The gear boxes 630, 630' are in turn mounted by suitable bracket assemblies 635, 635' on the rear or back side of the ear-like members 602, 602'. The gear boxes 630, 630' preferably may be comprised of a pair of equally matched right- and left-hand worm drive mechanisms, both of which drive the respective shafts 626, 626' in the same direction of rotation.

The two gear boxes 630, 630' are in turn connected by 10 a suitable arrangement to a single reversible electric motor 632 by a short shaft and universal couplings 634, 636 and 636', respectively, and a long jackshaft 638 and universal coupling 639, the latter shaft extending transversely across the back of the head assembly 100, as clearly shown in FIGURE 3.

Thus, it may be seen that the motor 632 may be rotated in one direction or the other in response to operation of remote control circuits leading to the operator's station 4. As the motor is energized, the shafts 634 and 20 638 will drive the worm gears in gear boxes 630, 630', which in turn drive shafts 626, 626' and pinions 628, 628', the latter in turn rotating the collars 610, 610' in whichever direction is desired, thus causing the head assembly 100 to traverse the length of the threaded assemblies 300, 300' in one direction or the other, as is desired.

Because of the fact that a great mechanical advantage is generated in the gear boxes 630, 630', a reasonably rated, high r.p.m. electric motor 632 will serve as a sufficient source of power from which to drive the nut-like traversing collars 610, 610'. Such drive mechanisms also inherently resist rotation in the opposite direction, i.e., rotation induced in shafts 626, 626', and thus act along with the shallow pitch of the threads on assemblies 300, 300' to lock the head assembly 100 to the assemblies 300, 300' in any one of its infinite positions of adjustment therealong.

In some cases it may be found desirable to reduce the friction between the external threads on the assemblies 300, 300' and the threaded interiors of the collars 610, 610', as well as between the friction surfaces defined by the cone-shaped surfaces 614, 614' on the collars and the bearing surfaces 608, 608' on the annular inserts 606, 606'. In such cases, because of the size of the components, a plurality of spring-loaded roller bearings 631 40 may be provided to define a roller surface between the threaded parts, while similar bearings 633 may be provided in the surfaces 614, 614', as is shown in FIGURE 6. Where such bearings are provided, it will be appreciated that the power requirements of the motor 632 45 will be reduced considerably.

Referring now to FIGURES 1, 2, 6 and 7, in particular, the manner in which the tube-like assemblies 300, 300' are supported in parallel spaced relation will now be described.

It will be remembered, that one of the objects of the invention set forth hereinbefore was that the entire apparatus is "free floating." By this term is meant that the entire stretching device is not rigidly anchored to either foundation or pit walls. This arrangement is most advantageous in that unequal stresses developed in the apparatus during a stretching operation may be to a considerable extent relieved by slight movements between the parts and, further, the sudden release of tremendous energy that occurs when a workpiece fails may be readily absorbed by some movement of the various components aside from the various safety features as have been, or will be, described.

Accordingly, each of the assemblies 300, 300' is "floatingly" fixed to the pit floor 1 through the medium of movable supports 500 and 550, 550'. Considering first supports 550, 550', of which each is identical to the other, it may be seen that each assembly 300, 300' comprises in effect a long hollow and externally threaded tube 310, 310'. As shown in FIGURE 6, the so-called "fixed"

head end of the tube 310 is capped at its end by a plate member 552. This plate member 552, as is member 552', on the opposite side of the apparatus, shown in FIGURE 2, is disposed vertically and is provided with a shallow cylindrical recess 554. The recess 554 receives the squared-off terminal end of the tube 310, the two being fixed together, as by welding or the like. The bottom portion of each vertical plate 552, 552' terminates in a box-shaped foot portion 556 having recessed side walls such that the top of this portion terminates in pairs of laterally projecting lips or flanges 568. It will be appreciated that these foot portions are so disposed that the sides parallel the longitudinal axis of the apparatus. Thus, the box-shaped portions may be seated in saddle members 570, which are comprised simply of channel-shaped members so disposed that their webs define a flat horizontal support, while their flanges define spaced guides to either side of the foot elements 556, previously described. The saddle members 570 each rest on suitable concrete or masonry piers 572, these piers 572 being formed on the floor 1.

The opposite or "movable" head ends of the respective tube-like assemblies 300, 300' are also "floatingly" supported, as well as laterally interconnected, as will be apparent when detailed consideration is given to FIGURES 2 and 7. In FIGURE 7, it will be seen that the "movable" head end of the threaded tube 310 also engages a shallow cylindrical recess 504 provided in vertical plate 506. The plate 506 also terminates in a box-like foot portion 508 having a longitudinal upper lip 512. Fixed between the vertical plates 506, 506' and rigidly connecting them together is a transverse housing 520. Preferably, this housing 520 is fabricated of heavy structural members, such as to be able to withstand considerable twisting and shear loads, and advantageously the housing may also serve to house various components, such as pumps, valves, accumulators, etc., which are utilized to obtain proper operation of the apparatus.

The entire assembly 500, then, rests on the foot portions 508, 508', which in turn rest on saddles 514, 514' comprised of angle-shaped members having one leg bolted to masonry or concrete piers 516 while the other legs 518, 518' are disposed vertically and because of the slide engagement with the foot portions 508, 508' act as guides to prevent lateral movement of the assemblies 300, 300' but at the same time permit longitudinal movement thereof.

Briefly recapitulating at this point, it will be apparent then that tube-like assemblies 300, 300' are supported on support assemblies 500 and 550, 550' in such a manner that the assemblies 300 may move longitudinally in the pit area defined by the end walls 3. The so-called fixed head assembly 100 also is movable with the assemblies 300, 300' being connected thereto through the screwjack mechanisms 600, 600' and this head assembly may be moved along the assemblies 300, 300' in either direction. Thus, the rectangle defined by components 300, 300', 500 and 100 is movable within the pit area and may be said to be "floatingly" supported therein.

Consideration will now be given to the manner in which the so-called "movable" head assembly is movably connected to the tubular assemblies 300, 300'. FIGURES 1, 2 and 7 disclose the arrangement in some detail. Thus, referring initially to FIGURES 1 and 2, it may be seen that the "movable" head assembly 200 is also provided with laterally projecting ear-like members 402, 402'. These ear-like members may be cast integrally, one-half with each of the upper and lower anchor beams and thus be joined by the oval strap members 204, 204', or the entire members may be single castings bolted or otherwise fixed to the respective anchor beams. Preferably, the former arrangement is to be utilized where possible. Since each of the members as well as its related parts is identical, a description of the assembly shown in FIGURE 7, the right-hand assembly 400 will serve as a description of both assemblies 400, 400', with prime numerals being

applied to those left-hand parts which may appear in FIGURE 2.

Accordingly, in FIGURE 7, it will be seen that the ear-like member rests on dolly 201. In this connection, it will be noted that the dolly 201 and the manner in which member 402 is attached thereto is identical in all four cases, in that all four dollies 101 and 201 are identical and identically connected to the respective ear-like members 402, 402' and 602, 602', respectively. Thus, the member 402 is provided with a depending base portion 403 comprised of an interrupted surface formed by block-like lugs 205. These lugs 205 are in interdigitated relation with respect to block-like lugs 207 provided on the top of dolly 201. The lugs 207 are further provided with pins 209 which fit into suitable apertures 411 in the base portion 403 of ear member 402. The dolly 201 is fabricated of conventional components and rides on a pair of four-wheeled trucks 213, 213' which are swivably connected thereto as by spherical joints 215, 215'.

As will be apparent in FIGURE 7, the ear member 402 is provided with a generally cup-shaped recess 404. The recess 404 extends substantially entirely through the ear member 402 and terminates at the rear face of this latter member in a reduced annular opening 406. The interior of the cup-shaped recess 404 further is provided with an inwardly projecting circumferential rib 408 and also includes an annular land 410 facing toward the front tube side of the ear-like member 402.

Within the recess 404 and in bearing engagement with the rib 408 is disposed a bell-shaped cylinder 420. This cylinder 420 which is supportingly carried by gripping head 200 comprises a main stretching cylinder of the apparatus. The outer surface of the cylinder is provided with a circumferential land 418 which, when the cylinder is positioned in the recess, is coaxial and concentric with respect to the land 410 provided on the interior wall 404 of the ear member 402. Between the two annular lands and in circumscribing relation with respect to the bell-shaped cylinder 420 is disposed a compression ring 422. This ring abuts both annular lands 410 and 418, respectively. The purpose of this arrangement will become apparent subsequently.

Through the interior of the stretching cylinder 420 passes a hollow rod member 302 which acts in the apparatus as a manipulating rod. This rod 302 has one terminal end attached to the end of the bell-shaped stretching cylinder 420. The connection between the two is effected by passing this end of the manipulating rod 302 through a suitable stepped aperture 424 provided in the closed end of cylinder 420. The rod 302 is provided with an annular neck 426 and a head 428. Inserted within the necked portion 426 of the rod 302 is a split retainer ring 430 having an outer diameter considerably greater than that of either the rod 302 or the head 428 provided thereon. Thus, the rod 302 passes through the smaller portion of the stepped aperture 424, the necked-down portion receives the split retainer ring 430, which is of an outside diameter equal to the inside diameter of the larger portion of the stepped aperture, and hence the ring 430 abuts against the annular land portion between the larger and smaller portions of the aperture to anchor the rod 302 to the cylinder 420.

In order to prevent displacement of the rod 302 and hence the retainer ring 430 from within the aperture 424 when the manipulating rod moves to extend the head assembly 200 away from the end of the tube-like assembly 300, the enlarged head 428 of the manipulating rod 302 is "squared off" and caused to be engaged by a disc-like cap plate 436 which also abuts against the end of the bell-shaped stretching cylinder 420, as well as against the back side of the ear-like member 402. This cap plate 436 is bolted or otherwise fixed to the stretching cylinder 420 by suitable fasteners 440. As may be clearly apparent from the above description when reviewed in the light of the showing in FIGURE 7, the cap plate 436

serves to lock the manipulating rod 302 to the stretching cylinder 420, as well as to lock the cylinder 420 to the ear-like member 402. The purpose of the ring 422 will also be apparent. Since the cylinder 420 will be imposed with extremely high pressures and loads, it is essential that such loads do not distort its shape. By supporting the closed end with the annular rib 408 in the interior of the recess 404, circumferential distortion of this end of the cylinder is reduced to an acceptable level. Additionally, the pressure of the compression ring 422 against the annular land 418 develops stresses which tend to reduce "bell-mouthing" or circumferential expansion of the exposed and open end of the cylinder. The stretching action is also transmitted from this ring 422 to the ear member 402, such that the loads imposed thereon are distributed throughout the member as evenly as is possible.

Considering further the assembly disclosed in FIGURE 7, it will be seen that the manipulating rod 302 is hollow and extends into the interior of the tubular assembly 300. This rod in turn is provided with a cylinder assembly 350, to be described subsequently in connection with FIGURES 8 and 13. Surrounding the rod 302 and slidable thereon is the stretching piston 442. This piston includes a skirt 444 and an internal sleeve 446 which slides on the manipulating rod 302, the sleeve being provided with an enlarged internal cylindrical wall adjacent one end into which is inserted a suitable hydraulic seal assembly 448. The head of the piston is also provided with a stop ring 450 which limits the amount which the piston 442 may move into the interior of the cylinder 420. The purpose of this stop ring is to prevent the cylinder from covering ports 304 provided in the manipulating rod 302. These ports 304 establish communication between the hollow interior of rod 302 and the interior of the stretching cylinder 420.

The skirt of the piston is provided with an annular periphery 449 which is adapted to engage an annular land 451 provided on the end of the assembly 300. Thus, the piston because of its slidable mounting on the rod 302 will be more or less "idle" on the rod until such time as its skirt edge 449 contacts the annular land 451 at which time it is capable in conjunction with the cylinder 420 of performing work.

Of course, the interior of the cylinder 420 may be so recessed as to receive suitable sealing means 452 which prevents escape of hydraulic fluid between it and the skirt 444 of piston 442, as is customary in the art.

Having thus described the manner in which the head assembly 200 is connected to the respective tube-like assemblies 300, 300', it will be apparent that as the manipulating rods 302, 302' are moved longitudinally the head assembly 200 will be moved toward and away from the ends of the stretcher assemblies 300, 300'. It will be further seen that if the head assembly 200 is disposed adjacent the ends of the assemblies 300, 300' such that the peripheral edges 449, 449' of the stretching pistons abut the annular lands 451, 451' on the ends of these assemblies relative movement between the stretching pistons and cylinders will occur if the cylinders are filled with fluid under pressure via the interior of the hollow manipulating rods 302, 302' and through the ports 304. It may also be seen that if the stretching cylinder assemblies were used to maneuver the "moveable" head 200 at all times, such as during loading and unloading of a work-piece, because of their large size, tremendous volumes of hydraulic fluid would of necessity have to be handled. As a result, any system and the components making up such a system would have to be proportionately large and of an unreasonable size. If, however, the ordinary manipulations of the head assembly 200 could be effected through more normal sized components, the hydraulic system could well be of normal size and such large volumes of fluids would not have to be handled. In order to accomplish this purpose, manipulating cylinder assem-

blies 350, 350' and sequence control valve assemblies 700, 700' are housed within the hollow interior of the tubes 310, 310' making up the tube-like assemblies 300, 300', as shown in dotted lines in FIGURE 2 and in detail in FIGURE 8. Again, since both assemblies 350, 350' and sequence valve assemblies 700, 700' are identical, only one of each assembly need be described in detail, prime numerals indicating similar parts on the opposite side of the stretching apparatus from that described in detail.

In considering FIGURE 8, it will be remembered that the hollow manipulating rod 302 is connected to the head assembly 200 by stretcher cylinder assembly 400, as previously described. Thus, movement of the manipulating rod 302 into and out of the interior of the tube-like assembly 300 will move the head assembly 200 toward and away from the assembly 300.

As seen, then, in FIGURE 8, the end of the hollow manipulating rod 302 which is housed within the threaded tube or tubular member 310 is enlarged to define a piston 306. The piston 306 in turn is housed within a tubular cylinder 308 in turn housed within and concentric with respect to the tubular member 310. Suitable seals 309 surround the piston 306 and engage the interior walls of the tubular cylinder 308 to define a hydraulic seal therewith. The tubular cylinder 308 is sealed at both ends by suitable heads 312 and 320, the head 312 being apertured to permit the rod 302 to extend therethrough, as shown in FIGURE 7. Thus, it may be seen that as pressure is applied to one side or the other of the piston 306, it will move within the cylinder 308 and either pull the rod 302 into the tube-like member 300 or push the rod 302 out of the member 300. Thus, the head assembly will also be moved toward or away from the respective assemblies 300, 300'. In addition, since the manipulating cylinder assemblies 350, 350' are of considerably less size than the stretcher cylinder assemblies 400, 400', the hydraulic system may operate satisfactorily with a minimum volume of fluid being handled and thus standard capacity components may be used therein.

In normal use, then, the manipulating cylinder assembly 350 will move the so-called "moveable" head 200 relative to the fixed head 100 during all manipulative steps, such as during loading and unloading of work-pieces in the apparatus. It is only during the actual stretching operation that the stretching cylinder assembly 400 is brought into play. Preferably, it is advantageous if the actuation of the stretching cylinder assembly 400 is "tied in" automatically with the operation of the manipulating cylinder assembly 350. To this latter end a novel sequence control valve, as well as a unique hydraulic system, is provided. The valve assembly 700 is clearly shown in FIGURE 8, while the hydraulic system is clearly shown in schematic form in FIGURE 13.

Considering first the components making up sequence control valve 700, attention is directed first to the valve assembly shown in FIGURE 8. It will be noted that all components utilized in the valve assembly are concentric and hence such concentric arrangement will be understood, though not specifically alluded to as such, in the description to follow. As seen in the drawing, the sequence valve assembly 700 is housed within an elongated cylindrical housing 702 having an open end 704 which is provided with an annular flange 706. The housing is fixed to the manipulating piston head 306 by bolts 708 or equivalent fastening means. The housing 702 is divided into two parts by a dividing wall 710 provided with a port 712 communicating with both of the chambers so defined. One of the chambers T serves as a tank, while the other houses the valve mechanism and is provided with a radial port 714 which communicates with the interior of the manipulating cylinder assembly 350.

Within the valve mechanism chamber, there is provided a hollow ported valve body 715 having a port 716 com-

municating with port 714, a radial port 717 in communication with an internal axial port or chamber 719 exhausting into tank T. The valve body also is provided with a small diameter axial port 721 in communication with a spring biased check valve 723 and also with a similar, though smaller, valve 725. Still another port 727, having one end communicating with the hollow interior of the valve body 715 and having its other end in communication with a port 729 provided in the manipulating piston 306, is provided with a restricted orifice in the form of apertured plug 731.

Within, and axially moveable with respect to, the valve body 715 is a cylindrical valve spool 730. This spool includes a central disc 733 provided with an aperture 735 and orifice 737. From the disc 733 extend skirts 739, 741, the former being provided with a port 745. The valve spool 730 is connected to a pilot piston 750. The pilot piston 750 includes an enlarged head 752 provided with the usual seals which rides in a longitudinal cylinder 754 suitably fixed within the valve body 715. The pilot piston 750 further includes a rod 756 formed integrally with the head 752 and also an annular shoulder 758 and a threaded end receiving a nut 760. The area of the rod 756 is such that the ratio of areas of the two sides of the piston 752 which are exposed to hydraulic pressure is two to one. In other words, using the usual calculations, there is twice as much force exerted on the head end of pilot piston 752 as can be exerted on the rod end thereof.

The head end of pilot cylinder 754 is in communication with a passage 757 in turn communicating with check valve 723. The rod end of this same cylinder is in communication through port 764 with previously described passage 727.

As has been set forth above, the pilot rod 756 is provided with an annular shoulder 758 and a reduced threaded end for receiving nut 760. The reduced end of pilot rod 756 is inserted within the aperture 735 in the central disc portion 733 of the valve spool 730 and is slideable with respect thereto. The nut 760 is applied to its threaded end and also engages the disc 733 while shoulder 758 engages the disc 733 from the opposite side. Since the reduced portion of the pilot rod 756 is of such a longitudinal length as to space the nut 760 and the shoulder 758 some distance apart it will be apparent that the spool 730 may move relative to the pilot piston 750 and vice versa.

Surrounding the pilot cylinder 754 and slideable longitudinally therewith is a cup-shaped spring biased stop member 784. This member is provided with an in-turned annular flange 776 adapted to engage an out-turned annular flange 768 provided on the end of pilot cylinder 754, such that the cup-shaped stop member 784 may not slip off of the end of pilot cylinder 754. A suitable coil spring 770 circumscribes the pilot cylinder 754 and bears against a shoulder 772 and also against an out-turned peripheral lip 774 provided on the cup-shaped stop member 784 to bias this member, such that flanges 776 and 768 are in contact. The manner in which the sequence valve 700, as shown in FIGURE 8, operates will be described now along with the hydraulic circuit used in conjunction therewith and shown schematically in FIGURE 13.

As shown, both stretching and manipulating cylinder assemblies 400, 400' and 300, 300' are represented schematically in FIGURE 13. Again, since both sides of the system operate identically, a description of the operation of one side will serve as adequate disclosure for both, like numerals, one set primed, indicating like parts.

The external system, shown in FIGURE 13, derives its pressure from a pair of identical pumps P, P' driven by a motor M. The pump P is connected on one side to a conduit 701 leading to the right-hand side of manipulating cylinder 350. The other side of pump P is connected to conduit 703 leading to the left-hand side of the

same cylinder 350. The conduit 703 is connected to maximum pressure relief valve 705 which exhausts through line 707 into tank T. Also connected to conduit 703 and venting into tank T through line 707 is a pilot-operated check valve 709. Interposed between the system operating both sides of the stretcher apparatus is a differential bleed-off mechanism, including valves 755, 755'. This mechanism will be described subsequently in connection with FIGURE 15.

The operation of the apparatus will now be described. In so doing, it will be remembered that all operator-operated controls are remote controls located at control station 4, shown in FIGURE 2. Considering now FIGURES 8 and 13, in conjunction with one another, it will be assumed, in order to establish a starting point for a complete cycle of operation, that a workpiece is in proper position, locked in the respective head assemblies 100, 200 in the manner previously described and that a stretching cycle is about to begin. It will be assumed, too, that the operating parts of the sequence valve assembly 700 are positioned, as shown in FIGURE 8. Also, it will be understood that movement of the control hands H to the right causes the stretching cylinders 420, 420' and thus moveable head assembly 200 to move to the right and vice versa.

Accordingly, the operator will move the control lever H toward the left-hand position L. The pump P will be energized to cause fluid to begin to build up pressure on the right-hand side of manipulating cylinder 350, thus forcing piston 306 and manipulating rod 302 to the left, as seen in FIGURE 13. Meanwhile, fluid will be exhausted from the left-hand side of the manipulating cylinder 350 through conduit 703 to the opposite side of pump P. Thus, moveable head assembly 200 is moved away from the fixed head assembly 100, and the workpiece will be subject to increasing tension.

It will be noted further that as the manipulating rod 302 moves the stretching piston 442 will be carried along with the stretching cylinder 420 and that the peripheral edge 449 of its skirt will be moved away from its engagement with annular shoulder 451 on the stretcher assembly 300. Thus, a gap is created between the skirt periphery 449 and shoulder 451.

Because the valve spool 730 of the sequence control valve 700 is positioned as shown in FIGURE 8, the port 714 is blocked, thus no fluid can flow through this port into the interior of hollow manipulating rod 302. Because of this, no fluid can enter the stretching cylinder assembly 400. However, the increasing pressure from the pump P does pass through passage 721 where it acts upon check valve 725. It has been found that this valve may preferably be set at 2500 p.s.i. such that it will not open until this pressure is reached. Thus, manipulating cylinder 350 continues to act until the resistance of the workpiece to stretching increases to a point such that the pressure on the left-hand side of the manipulating piston reaches 2500 p.s.i. At this point, check valve 725 opens admitting fluid to passage 757 and thus pressure is applied to the head end of pilot cylinder 754 and pilot piston 750 moves to the left. Eventually, shoulder 758 engages valve spool 730 and moves the spool to the left. The fluid on the rod end of pilot piston, meanwhile, exhausts through port 764, passages 727 and 729 to the exhausting or left side of the manipulating piston 306.

As the shoulder 758 on pilot rod 756 engages the central disc 733 of valve spool 730, this spool will move to the left until ports 714 and 745 are aligned. As this happens, pressure is admitted into the hollow interior of manipulating rod 302 and is carried to ports 304. Thus fluid is admitted into the stretching cylinder assembly 400.

It will be noted that the central disc 733 of valve spool 730 includes passage 737. Thus as pressure builds up against the left-hand side of the spool disc, it will also

build up on the right-hand side thereof, bleeding through passage 737 and thus the spool reaches ultimately a balanced equilibrium condition.

The stretching cylinder assembly 400 is now being energized and the initial effect of the pressure applied therein is to cause movement of the stretching piston 442 along the manipulating rod 302 toward the right until its periphery 449 again abuts annular shoulder 451, thus closing the previously described gap therebetween. Once this abutment occurs, it will be appreciated that pressure then can only cause cylinder 420 to move away from assembly 300 and thus moveable head 200 is urged with even greater force away from the fixed head 100 because of the great size of the stretching cylinder assembly 400 added to the already exerted stretching load imposed on the workpiece by manipulating cylinder assembly 350.

As has been indicated, the stretching cylinder 420 is of large diameter. In fact, to be more specific, this cylinder is on the order of 56 inches in diameter. Thus, it will be obvious that as this cylinder is energized, its action because of the small volumes of fluid first admitted would be so slow as to be undesirable. Accordingly, since the volume of fluid is relatively small, some means must be provided wherein an additional volume of fluid may be pumped into the system. The fluid may be obtained from the tank T. This is effected through a pilot operated check valve 709. This valve is provided with a pilot line 711 connected with conduit 701. At any time there is pressure in conduit 701 in excess of approximately 30 p.s.i. the pilot operated check valve 709 is held open so that oil will flow freely from the tank T through conduits 707 and 703. Since the speed of the stretcher under manipulation during the previously described manipulating cycle will decrease suddenly due to the volume of oil demanded by cylinder 420 it will be necessary to increase the output of pump P by shifting the control. Thus, the stretching cylinder 420 is adequately supplied with fluid and stretching of the workpiece continues at a controllable speed. By measuring the amount in which "moveable" head assembly moves away from "fixed" head assembly 100, the amount of stretching of the workpiece may readily be determined and from this the degree of stress relief thereof readily calculated.

Assuming the stretching cycle is completed, the entire system then must be de-energized and finally the stretched workpiece removed from the apparatus.

The operator will move control lever H to an interlocked intermediate right-hand position R₁, as indicated in FIGURE 13, preferably this lever is locked in this position by a pressure control switch tied into the manipulating cylinder 350 such that it cannot be moved to full right-hand position R₂ until the apparatus is de-energized. The lever H having been moved to the R₁ position, decompression takes place. Fluid under pressure will flow from the stretcher cylinder assembly 400 through port 304, manipulating rod 302 to the right-hand side of the manipulating rod cylinder assembly 350. Simultaneously, the pump P is reversed and begins to relieve the pressure on the right-hand side of manipulating cylinder 306 through the conduit 701, the reversed pump P acting as a metering device to control the rapidity of the pressure drop.

While metering high pressure fluid from the right side of the manipulating cylinder, the pump P passes fluid through conduit 703 and into the left-hand side of the manipulating cylinder 308. This pressurized fluid passes through orifice 731, passage 729 in the manipulating piston 306 into passage 727, through port 764 and to the left-hand side of pilot piston 750.

However, because of the mentioned two-to-one ratio between head and rod end this pilot piston 750 cannot move until the pressure on its head end is reduced to such a degree that the pressure on the rod end will overcome its disadvantage. Thus, the valve spool 730

is held with ports 745 and 716 aligned until the pressure on the stretching cylinder assembly 400 is completely relieved. Due to the bleed through orifice 737 in spool disc 733 the pressure on the right-hand side of the spool is also relieved and eventually the system reaches a condition of equilibrium. It will be apparent that during the time pressure is maintained in passage 721 it is also acting on check valve 723 supplementing its normal closing bias. However, as the pressure in passage 721 is reduced the fluid under pressure entrapped in the head end of the pilot cylinder 754, plus the pressure against the rod end of pilot piston 750 acting through conduit 727 and port 764 from the left-hand side of the manipulating cylinder 350 will unseat this valve. Thus, pilot piston 750 will move slowly toward the right until the nut 760 drags the sequence valve spool 730 back against the stop member 784, thus again blocking port 714.

At this point the so-called "fixed head" is released from the workpiece W and the control lever H is swung to the left-hand L position again. The pump P reverses and again pressurizes the fluid which flows through conduit 701 into the right-hand end of manipulating cylinder assembly 350 while the left-hand end of this cylinder exhausts through conduit 703. Since the workpiece W is released the pressure in the system will never reach 2500 p.s.i. and hence, sequence valve 700 will not move. Thus, the manipulating rod 302 will cause "moveable" head 200 dragging the workpiece free of its gripping mechanism. Again a gap is opened between the stretching cylinder periphery 449 and shoulder 451. As the workpiece is freed the gripping mechanism of "moveable" head 200 is released and the workpiece, suspended now by overhead crane, is removed.

A new workpiece is lowered into place and clamped in "moveable" head 200. During this time control lever H is in centered or neutral position and with the exception of the gripping mechanism of "moveable" head 200 the apparatus is at rest.

Once clamped in "moveable" head 200, the workpiece must be moved toward and clamped in "fixed" head 100. The movement of head assembly 200 toward head assembly 100 is effected by again moving the control lever H to the right-hand position, in this case, to the full right-hand position R₂.

The pump P is again reversed and fluid flows out of the right-hand side of the manipulating cylinder assembly 350 through conduit 701 to the pump P and from the pump P through conduit 703 to the left-hand side of the manipulating cylinder 350. Again because the pressure is low no action of sequence valve assembly 700 takes place.

However, since the new workpiece unstretched is shorter than the stretched workpiece previously removed, it will be apparent that the stretcher piston skirt will again approach the column assembly 300, periphery 449 again contacting shoulder 451. Because of this the fluid entrapped in stretching cylinder 400 will be pressurized and thus will try to exhaust through hollow manipulating rod 302.

Referring again in particular to FIGURE 8, it will be seen that the pressurized fluid will bear against the disc 733 of the sequence valve spool 730 and as the pressure increases will cause this spool to compress spring 770 until port 745 aligns with port 717. As the stretcher piston 442 is forced into the cylinder 420 the fluid will pass from stretcher cylinder 420 through manipulating rod 302, port 745, port 717, passage 719 and thus into tank T.

As soon as the end of the workpiece approaches head assembly 100, the hold-down roll cylinders 152 and rods 154 previously described are energized and the end of the workpiece is guided between gripping members 118, 118'. All the while fluid is exhausting from the stretcher cylinder assembly 400 into the tank T. The volume of fluid so exhausted will be approximately equal to that taken in

during the previous stretching cycle. The members 118, 118' are then clamped on the workpiece. The handle H returned to center and a new stretching cycle may begin.

Note that, as soon as relative movement between stretching piston 442 and cylinder 420 ceases, the spring 770 will bias the sequence valve spool back to its neutral position as shown clearly in FIGURE 8. A complete stretching, decompression, unloading and loading cycle has thus been described.

From the operational description above it may be seen that a novel system and valve assembly is provided which enables operation of the apparatus without inordinately large hydraulic components and in which the controls required to operate the device are reduced to a minimum. Of prime interest is that fact that the apparatus utilizes no articulated connections between the gripping head assemblies 100, 200. Thus, all loads created during stretching are substantially linear loads and, because the assemblies 300, 300' act in substantially the same plane as that in which the workpiece rests, twisting forces on the apparatus are reduced to a minimum.

As in the case of the gripping mechanisms described above, it is most desirable that a safety device be incorporated in the hydraulic system which performs the stretching and manipulating action of the apparatus to protect its various components in event of breakage of a workpiece. The location and manner of operation of such safety devices will now be described in detail.

In FIGURE 8 there is shown a plurality of cylindrical chambers 902 positioned in the piston 306. In each of these chambers is positioned a pressure relief device 920, each chamber and each device 920 comprising a safety valve assembly 900 of which there are at least four in piston 306. Since all of the assemblies 900 are similar only one need be described. Accordingly, referring to FIGURES 8, 10, 11 and 12, it may be seen that in communication with the chamber 902 are an inlet port 904 and an outlet chamber 906 in communication with an outlet port 908. Thus, it will be seen that the chamber 902 and the respective inlet and outlet ports establish communication through the manipulating piston 306. Within the cylindrical chamber 902 there is provided a spring-seated relief valve 920.

It will be remembered that during the stretching cycle high pressure is being exerted on the right-hand side of manipulating piston 306. Thus, if during stretching a workpiece should break the tendency is for this piston as well as the head assembly 200 to move with tremendous force to the left. Naturally since there is fluid in the left-hand side of the manipulating cylinder assemblies 350, unless some means is provided to absorb the shock, since the fluid nearly is incompressible, severe damage might result to either the manipulating cylinder, the stretching cylinder assembly 400 or the hydraulic components in the stretching system shown in FIGURE 13. However, if the fluid on the left-hand side of the manipulating piston 306 is passed to the right-hand side through the piston 306 several results take place. First of all the shock is converted to work by moving fluid under pressure from one side of the piston to the other. Secondly, fluid is bled away from the left-hand side and thus, the piston 306 can move, this fluid being passed to the right-hand side to obviate the necessity of supplying additional fluid to the right-hand side of manipulating piston 306. It is this function that the safety valve assemblies 900 serve.

Accordingly, each valve assembly 920 comprises an annular insert 922 having a conical seat 924. Biased against the seat 924 by an oil spring 926 is a moveable valve plunger 928 having a conical end 930 adapted to rest and seal against the conical seat 924. The plunger 928 is hollowed out and receives interiorly an end of a guiding and stationary piston 932. By forming a series of grooves around the outside of this piston a so-called

"labyrinth" seal is formed between the exterior of the fixed piston 932 and the interior of the plunger 928. The spring 926 circumscribes the stationary piston 932 and bears at one end against the flanged end of the plunger and at its other end against a closure disc 934, having therein a series of symmetrically arranged ports 936 communicating with annular outlet chamber 906.

It will be noted that the plunger 928 is of a slightly smaller diameter than that of the interior wall of a cylindrical tube 938 which circumscribes the entire assembly and bears against the seat or insert 922 to keep it in place. Thus, the plunger 928 is provided with a series of radial guide fins 940 along with an annular shoulder 942 which act to center the plunger in the tube 938 and prevent it from locking therein. The skirt of the plunger is provided with converging ports 944 which put the chamber formed between the exterior of the plunger 928 and the tube 938 in communication with that area of the chamber 902 behind the plunger 928. It will also be noted that the end of plunger 928 is provided with a port 950.

The operation of the device is as follows: Assuming that there is fluid in the passage 904 it will be seen that this fluid will pass through port 950 and a portion will become entrapped within the chamber defined by the interior of the plunger and the end of fixed piston 932 disposed therein. Similarly the exterior of the plunger will be surrounded by high pressure fluid from the right side of the manipulating cylinder assembly 350 through ports 908, 936, etc. The entire relief valve assembly ordinarily remains at rest. Suppose then a workpiece fails suddenly. The piston 306 begins to try to accelerate rapidly to the left. Almost instantaneously there is a build-up of pressure in port 904 and a drop in pressure in port 908. Because of the fact that port 950 allows oil under high pressure to enter plunger 928 and exert pressure against piston 932, this pressure will tend to increase the setting pressure of plunger 928 against its seat 924. This force supplements the spring pressure 926 to combine with the spring pressure and regulate the pressure required to open the relief valve. This pressure has arbitrarily been selected at 6000 p.s.i. This device is what is commonly referred to as a hydraulically balanced check valve. When the pressure exerted is sufficient to overcome this combined pressure, plunger 928 is lifted off its seat 924. High pressure fluid then passes around the outside of the plunger and escapes through ports 936, chamber 906 and ports 908 to the right-hand side of the manipulating piston 306. Because of the various restricted passages the fluid is caused to heat up and thus the shock energy is turned to heat energy by working of the fluid.

As soon as the initial shock load drops and the pressures within and without the plunger 928 equalize, the bias of the spring 926 forces the plunger to reseal against seat 924 and a condition of equilibrium exists therein. Thus, the assemblies 300, 300', the stretching cylinder assemblies 400, 400' and the external system shown in FIGURE 13 are protected against sudden surges of pressure while pressure in the system is relieved.

As thus far described, all safety devices incorporated in the apparatus have been directed to the stretching mechanisms in head assemblies 100 and 200 and to absorbing the shock loads imposed in the hydraulic system during the movement of the "moveable" head assembly 200 when a workpiece fails. However, since the assemblies 300, 300' as well as the "fixed" head assembly 100 are not anchored but are floatingly attached to the tubular support bases 516, 516' and 572, 572', the "fixed" head assembly 100 as well as the tube-like assemblies 300, 300' will, as a workpiece fails, be subject to tremendous energy, tending to drive these components and the head assembly 100 to the right as viewed in FIGURES 1 and 2.

In order to limit the travel of the "fixed" head assembly 100 and tube-like assemblies 300, 300' due to shock,

and at the same time to reorient the entire apparatus back to normal, the tubular supports 550, 550' are moveably fixed to the vertical pit end wall 3 by a pair of identical shock absorber devices 360, 360' through the medium of a pair of piston rods 362. Each piston rod 362 is formed integrally with a piston 364 which is slidable within a cylinder 368. As shown in FIGURE 9, cylinder 368 is anchored to pit wall 3 by any suitable means and includes a closure member 370 through which the connecting rod 362 passes.

Referring to FIGURE 9, it may be seen that one end, the head end of cylinder 368, is provided with ports 372 in communication with a gas accumulator of conventional form. The accumulator is charged with an inert gas under pressure and the head end of cylinder 368 is filled with pressurized inert gas.

The closure member 370 is provided with an internal chamber 374. This chamber 374 is in communication with a source of hydraulic fluid not shown, such as a tank or the like. In communication with this chamber are a plurality of interspaced ports 375, 376. Ports 376 (only one being shown) comprise small diameter bleed holes to the interior of cylinder 368 while the ports 375 (also only one shown) normally closed by lightly biased poppet valves 377 are also in communication with the cylinder interior. Each of the valves 377 is comprised of a head 379, a stem 381, a guide 383. The end of the stem 381 is provided with nuts 385. Circumscribing the stem and bearing against both the guide 383 and the nuts 385 is a valve biasing spring 384 which keeps the valve head 379 seated against the annular wall defining port 375 with a very light seating pressure.

During all normal operation of the stretching apparatus the piston 364 is as shown in FIGURE 9, having been pushed toward the rod end of the cylinder 368 by the pressure of the gas entering port 372. Also, the small volume of the cylinder 368 to the right of the piston 364 will also be filled with fluid from chamber 374 which has bled through the drilled ports 376. However, when a workpiece fractures, the piston rod 362 and hence piston 364 will be driven toward the pit wall 3. This compresses the gas on the head side of cylinder 368 and piston 364 may move toward the head end. The compression of the gas in the cylinder 368 generates a great deal of heat which is dissipated to the air through the metal cylinder 368. Again the conversion of energy from one form to another acts to absorb shock. Since the gas acting on the head end of piston 364 is under pressure, it will be apparent that unless some means is provided to absorb rebound shock as the gas in the head end of piston 364 again exerts pressure thereon, there will be considerable rebound of the piston 364 with great shock being transmitted back to the tubular assemblies 300, 300'. This rebound shock is controlled by the valves 377 and bleed ports 376. Ordinarily, the normal position of valves 377 in seating relation with respect to the port 375 is such as to close these ports and thus fluid acting through chamber 374 will be retained therein except for that which has passed through ports 376. However, when the piston 364 is driven to the left, as viewed in FIGURE 9, by the tremendous force produced as a result of breakage of a workpiece, the lightly biased poppet valves 377 are snapped open and thus, the rod side of cylinder 368 will be filled with hydraulic fluid drawn from chamber 374 and the source of fluid connected thereto through both ports 375 and 376. Thus, the piston cannot fly back to its normal position, because of the fact that the hydraulic fluid thus admitted to the rod side of the piston is incompressible and further due to the fact that as soon as pressure is exerted thereon the inlet poppet valves 379 again close blocking ports 375.

However, since the ports 376 are open the fluid drawn into the rod end of cylinder 368 will be gradually bled through these ports back into the chamber 374. By

proper selection of size or calibration, then, the normal rebound of piston 364 may be so controlled as to be reduced to a quick yet acceptable deceleration action as the gas expends additional energy against the piston 364 to return it against the gradually bled-out fluid until the piston 364 returns to its normal "at rest" condition as shown in FIGURE 9.

It will be appreciated that since the rods 362, 362' are connected to the stretcher tubular assemblies 300, 300' as has been described, this snubber not only serves to absorb shock produced by breakage of a workpiece during stretching, but further acts to reorient the assemblies 300, 300' and the stretcher head assembly 100 which also have moved back to their normal positions.

Considering now both FIGURES 13 and 15, it may be seen that means are provided which act between the two stretcher assemblies 300 and 300' whereby equalized movement of both manipulating pistons and stretcher pistons is assured. Such an arrangement is shown by the dotted lines in FIGURE 13 and in detail in FIGURE 15.

In its simplest form and shown schematically in both drawings, the coordinating apparatus may comprise a pair of drums 780 and 780' mounted on the body of the assemblies 300, 300'. A cable 781, 781' is passed around each of the drums 780, 780' and each is fixed at one end, in some suitable manner, to the body of a stretcher cylinder 400, 400'. Preferably, the drums 780, 780' are a self-reeling type, that is, some means is provided whereby the drums are always biased to cause the cables 781, 781' to be under tension tending to reel the cable upon the drums 780, 780'. Such devices are well known and need not be described in detail. Thus, it will be apparent that as each cylinder assembly 400, 400' moves away from its associated tubular assembly 300 or 300', the cables will be unreeled from the drums and conversely when the stretcher cylinder assemblies 400, 400' approach their respective tubular assemblies 300, 300' the cables 781, 781' will be reeled upon the drum. As indicated schematically in FIGURE 13, these two drums are connected by means of shafts 751, 751' to a suitable differential mechanism 782. It will also be apparent from an inspection of FIGURE 15, that the cables 781, 781' will be reeled and unreeled upon the drums in opposite directions. Shafts 751, 751' are thus caused to rotate in opposite directions. Thus, the small bevel gears 783, 783' carried on the inner ends of shafts 751, 751' will be caused to rotate at the same rate of speed but opposite directions. In mesh with and between bevel gears 783, 783' are a group of two or more (two being shown) carrier gears 761. These gears are so-called because they are mounted upon and carried by a differential carrier 759 which is in turn fixed to and rotatable with a large ring gear 784.

So long as the rates of rotation of the respective drums 780, 780' and hence gears 783, 783' are equal and opposite, it may be seen that the small carrier gears will rotate and since the rotational forces acting thereon are equal and opposite, their axes will remain fixed, i.e., no rotational forces will act on the carrier gears 761 and ring gear 784 which would cause rotation thereof. The carrier gears are then merely idling.

However, should one or the other of the drums 780, 780' be rotated at a faster rate than the other, unbalanced rotational forces are created which act on the carrier gears causing them not only to continue rotation, but also to transmit a rotational load on the carrier such that the carrier gears 761 as well as ring gear 784 are caused to rotate. Since the ring gear is in mesh with a small pinion gear 763 which rotates about a fixed axis, the rotation of the ring gear is imparted thereto. Obviously, depending on the relative rates of rotation of the bevel gears 783, 783', the direction of rotation of the ring gear 784, and hence pinion 763, may be one way or the other.

The pinion 763 thus may be connected by any suitable means to a pair of valves 755, 755' interconnected by lines 785, 785' and 786, 786' into lines 701, 701' and into tank lines 707, 707' such that one or the other of these valves may bleed high pressure from lines 701, or 701', as the case may be. Thus, if a differential in rate of movement of one of the manipulating cylinder assemblies 350, 350' or stretching cylinder assemblies 400, 400' exists, this differential will be transmitted to pinion 763 in the manner indicated. Movement of this pinion in turn will actuate either one or both of the two valves 755, 755' bleeding off pressure from the faster moving side until the rates of both sides of the stretcher mechanism equalize at which time carrier gears 783, 783' will again merely idle. In so doing these valves would bleed off pressure from lines 703, 703' through lines 786, 786' allowing pressure to be vented through conduit 785, 785' to the tank T.

Referring briefly to FIGURE 16, a novel strap assembly employed for the anchor straps 104, 104', 204, and 204' is shown which may be used to join the anchor beam 20 castings 102, 102' and 202, 202' used in the respective head assemblies 100 and 200. Such a strap assembly comprises an inner oval member ring 910 formed of flat mild steel members, welded as indicated, and in turn surrounded by a series of shrunk in place laminated members 910' or a lamination consisting of a continuous strip of thin material wound on the inner oval ring member. The inner ring may be comprised of two arcuate members 911, 911' and two straight members 912, 912', all of which are welded to define an oval adapted to surround the respective castings. The purpose of this arrangement is twofold. By the use of small laminate members stresses created in the strap assembly will be primarily in tension while the normal reversal of stresses occurring at the ends of the ovals may change from compression adjacent the arcuate segments 911, 911' to tension toward the outer end of the ring without development of any undue loads in the overall assembly. In other words, the superposed laminations develop slip planes between one another such that the infinitesimal movements which occur during highly loaded conditions may do so without creating internal shear planes in the strap assembly as is the case where these assemblies are simply shrunk-in-place forged components.

A further advantageous embodiment of this invention is shown in FIGURES 17-31, inclusive. In considering these latter figures of the drawings, it will be apparent that many of the subcombinations which are incorporated in the apparatus shown therein are duplicated. For clarity, therefore, reference numbers together with the letters (a) and (b) will be used to designate like parts. Additionally, it will be noted in FIGURES 17, 18, 19 and 20 that there is a workpiece gripping head at either end of the apparatus. Since one of these gripping heads is fixed during the stretching cycle while the other moves, this provides a distinction between the two which, for purposes of avoiding confusion, will be maintained throughout the specification and claims. Accordingly, as viewed in FIGURES 17 and 18, the workpiece gripping head located at the right-hand portion of the drawings is the "fixed" head while that on the left-hand portion of the drawings comprises the "moveable" head.

In considering FIGURES 17 and 18, it may be seen that the apparatus is comprised of a pair of gripping heads 100a, 200a disposed in face-to-face relation and interconnected by a pair of parallel tubular assemblies or elongated tube-like means 300a, 300b. These assemblies 300a, 300b include a pair of stretching motors 320a, 320b interposed intermediate the length of the tubular assemblies, the function and mode of operation of which will be subsequently described.

The stretching motors 320a, 320b rest upon and are moveable on a pair of suitable saddle-like support members 301a, 301b. As is also apparent in FIGURE 18, the

5 right-hand ends of the tubular assemblies rest on and are moveable with respect to the saddle supports, while the left-hand ends of the tubular assemblies rest on a wheeled supporting frame 330a. Extending from each of the latter ends of the tubular assemblies are rod members 400a, 400b which will be described in more detail hereinafter. These rod members 400a, 400b are fixed by means of a pair of combined and identical anchors and manifolds 420a, 420b to a suitable foundation which in this case is defined by a rectangular pit 10a having a floor 1a including a longitudinally depressed central portion 2a and suitable stepped end walls 3a and 7a.

Because of the unique design and mode of operation of the apparatus, the pit may be constructed of conventional materials such as reinforced concrete of the usual thicknesses. Since the prime function of the foundation is one of support rather than that of a load-absorbing structure as is the usual practice with such metal-stretching devices, no unusual or cumbersome foundation supports are required.

The upper floor area of the pit is provided with spaced pairs of rails 4a, 4b and 5a, 5b between which are disposed drawbar members 6a, 6b, as will be described in detail hereinafter. Upon these rails rest a plurality of wheeled trucks 90a. These wheeled trucks 90a comprise the supports for the respective "fixed" and "moveable" gripping heads along which each may be moved in a manner to be described. These same rails 4a, 4b, and 5a, 5b also guide and support the wheeled supports 330a for the left-hand ends of the tubular assemblies as previously mentioned.

The right-hand ends of the parallel tubular assemblies 300a, 300b are connected to foundation wall by means of a pair of shock absorption devices 360a, 360b the function of which will be subsequently apparent.

As thus far described, it will be apparent that a workpiece, such as a plate, which might be gripped by the two heads 100a, 200a can be stretched if the two heads are moved apart. The two stretching motors 320a, 320b, serve this function. However, remembering that the apparatus must be loaded, be unloaded, accommodate material of different lengths, etc., it will also be apparent that some means must be provided to effect these operations. Considering the fact that the stretching motors 320a, 320b must be of considerable size to develop the required stretching forces, it will be seen that it is totally impractical, if not impossible, to provide these motors with a long enough stroke to perform these ancillary operations. Moreover, if these motors were used for all the mentioned operations, the volume of hydraulic fluid that would have to be handled constantly would be so great that normally available pumps, conduits, etc., would not suffice to provide for a complete cycle of operations in a reasonable time thus necessitating the use of especially constructed components and the overall cost of the apparatus would be prohibitive.

The present invention contemplates the use of smaller manipulating motors which may be used to perform all the usual movements of the apparatus. The larger stretching motors are thus brought into use only during the actual stretching portion of a normal cycle of operation, resulting in a reduction of cycle time, size of pumps, conduits, etc., such that readily available components—i.e., pumps, control valves, conduits and the like—may be used to actuate and control the apparatus.

To this end and considering in particular FIGURES 19 and 20 wherein one tubular assembly is shown in section, it will be seen that the tubular assemblies 300a, 300b are in fact each formed of hollow tubular portions 302a, 304a, 306a and 308a, which portions are joined in coaxial concentric relation by suitable lap welded joints. It will be noted that the tubular sections 304a and 306a have a much greater wall thickness than sections 302a and 308a. The reason for this is that the principal loads imposed on these tubular assemblies occur between the

ends of these thicker sections 304a and 306a as will become apparent subsequently.

These sections 304a, 304b, 306a and 306b are further provided on their outside surfaces with a regular circumferential pattern of thread-like projecting ribs 312a, 312b, 314a, 314b, 316a and 316b. As may be seen in FIGURE 18, the pattern of ribs 316a provided on section 306a is substantially continuous throughout its length, the ribs being arranged in circumferentially spaced linear groups around the surface of this section. These longitudinal linear groups of ribs are spaced apart such that between each two adjacent groups are interspersed projection-free areas of similar dimensions as that embraced within the ribbed areas.

This circumferentially spaced arrangement of the thread-like projections or ribs 312a, 314a is also repeated on the peripheral surface of the section 304a. In this case, however, rather than being continuous the ribs are arranged in longitudinally spaced groups. The purpose of this arrangement will subsequently become apparent.

As may also be seen in FIGURES 19 and 20, the outermost ends of each of the sections 302a, 302b are affixed to a wheeled truck 330a comprised of face plates 332a, 332b welded to the ends of the sections. Each face plate 332a, 332b is in turn welded to a fabricated frame 334a which is carried by the wheels 336a. Suitable gussets 338a complete the assembly and tie the face plates 332a, 332b rigidly to a frame 334a.

The opposite ends of the tubular assemblies 300a, 300b comprised of the terminal ends of the tubular portions 308a, 308b are fixed to a similar pair of face plates 342a, 342b. These face plates 342a, 342b instead of being mounted on a wheeled truck, however, are mounted on slides 346a and 346b which ride in U-shaped saddle members 348a, 348b. Again suitable gussets connect the face plates rigidly to the slide members. Each of the face plates 342a, 342b is further releasably affixed by means of couplings 352a, 352b to piston rods 362a, 362b to be described. These piston rods 362a, 362b are moveable into and out of the shock absorbers 360a, 360b, the latter being in turn immovably fixed to the end wall of the pit area. The operation of these shock absorber devices 360a, 360b will be described more fully hereinafter.

Considering now the left- and right-hand portions of FIGURES 19 and 20, respectively, it will be seen that the right- and left-hand portions of a tubular assembly are not directly connected to each other. Rather, these two portions are indirectly connected in one tubular assembly, for example, through the medium of an internally bored and parted manipulating rod 400a, together with its cylinder 304a, and stretching motor 320a in a unique back-to-back or abutting arrangement or fashion which eliminates the necessity for large, complicated castings.

Considering for the moment FIGURE 20, it will be seen that the stretching motor 320a is comprised of a large cylinder barrel 322a which is initially formed with open ends. Into one end of the cylinder barrel 322a is introduced a plug 324a which plug is apertured at its center and is further provided with outer seals 326a. Thus, the plug forms a closure or bottom for the "fixed" head end of stretching motor 320a. In order to keep the plug 324a in place, it will be seen that the central aperture therein receives the end of the manipulating rod 400a. This rod 400a thus passes through the plug 324a and is provided with a stop or split lock ring 328a which prevents the rod 400a from disengaging from the plug. At the same time, the thickened wall portion of assembly 300a is caused to fit into a recess 361a provided in the "fixed" head side of the plug 324a. The diameter of annular recess 361a as well as assembly section 306a being larger than that of manipulating rod 400a, the internal surface of assembly section 306a is machined to admit the extreme end of the rod 400a as well as lock ring 328a whereby the end of the assembly section 306a fits within recess 361a. A further lock ring 333a fits in

a suitable annular groove provided on the outer surface and adjacent the end of the assembly portion 306a. Ring 333a, which is also split, is bolted or otherwise secured to plug 324a, thereby anchoring assembly section 306a and ring 328a to plug 324a. Thus, plug member 324a cannot move in one direction due to lock ring 328a and since manipulating rod 400a is fixed to anchoring manifold 420a and by lock ring 333a to plug 324a, the latter is rendered immobile in the end of cylinder barrel 322a and serves to close the end thereof.

Referring back to FIGURE 19, it will be seen that manipulating rod 400a is comprised of an internally bored and parted rod assembly including a piston portion 402a surrounded by suitable seal rings 403a. This piston 402a called the manipulating piston is housed within the hollow tubular portion 304a of the assembly 300a. When it is remembered that the manipulating rod 400a is fixed in position, it will be obvious that the assembly portion 304a defines a cylindrical sleeve which will move relative to the manipulating rod 400a in either of two directions. In other words, the described arrangement comprises a hydraulic motor assembly including a piston and cylinder 402a and 304a, respectively, wherein, rather than with the piston 402a moving within the cylinder portion 304a as is conventional, the piston is held stationary while the cylinder moves. To this end both the outermost ends of tubular portions 302a and 304a are provided with suitable seals to form a closed cylinder which, when supplied with hydraulic fluid to either side of cylinder or tubular portion 304a will be moved to the right or left as viewed in FIGURE 19.

Returning briefly to the stretching motor assembly 320a, it will be seen that in addition to the cylinder barrel 322a and the closure plug 324a, this assembly also includes a skirted piston 325a having a central aperture 327a which surrounds the fixed head side of manipulating rod 400a. It will be noted that this central aperture 327a is somewhat larger than the diameter of the rod 400a but that the piston is slidably centered thereon by means of closure and seal assembly 329a surrounding the manipulating rod 400 and by piston seal assembly 331a which engages the inner wall of the cylinder barrel 322a.

Of prime importance is the fact that the moveable assembly portion 304a is provided with an annular land or shoulder 305a on its right-hand end, as viewed in FIGURE 19, while the central skirted portion of stretching piston 325a is provided with a similar annular land 335a also as seen in FIGURE 19. The purpose of this arrangement will become apparent particularly with reference to the detailed description of FIGURE 19. It will, of course, be appreciated that a similar arrangement is used insofar as assembly 300b and rod 400b are concerned and that, where shown, the reference letter "b" indicates identical parts. Although the operation of the piston 325a is disclosed more fully hereinafter, it might be well to indicate briefly at this time how this piston operates. This piston 325a acts as a stretching piston and it is actuated during the stretching operation after there is a pressure buildup in the central passage 412a of manipulating rod 400a at which time fluid is evacuated from openings 323a into the opening 327a between piston 325a and plug 324a. This, in turn, causes the piston 325a to move to the left as shown in the several figures of the drawing and exert further pressure on the sleeve or tubular assembly portion 304a by virtue of the abutting relationship between the shoulder 335a of the stretching piston and the shoulder 305a of the moveable assembly portion 304a to which head 100a is attached.

Having described the two extensible assemblies 300a, 300b, including stretching motors 320a, 320b, attention is now directed to FIGURES 17, 19, 20, 23, 24 and 25 of the drawings. These figures deal specifically with the workpiece gripping heads and their operation and the manner in which these assemblies are fixed to assemblies 300a, 300b.

From FIGURE 17 it may be seen that the gripping heads are identical and that head assembly 100a comprises the moveable head, while head assembly 200b comprises the so-called "fixed" head, and that FIGURES 21 and 23, respectively, are enlarged views showing the front and rear of the so-called moveable head assembly 100a, FIGURE 21 being an overall view while FIGURE 23 is an enlarged view of a portion of the rear of the same assembly. Since both head assemblies are identical, a description of assembly 100a should serve for both.

Considering initially FIGURE 21, it may be seen that the gripping head assembly 100a includes two basic upper and lower beam members 20a and 30b, respectively. These two beam members are substantially identical and include deep sectioned central portions 22a, 32a, which define a central horizontal planar slot S₄ between their opposed upper and lower inner faces. As is readily apparent, the ends of each of the beams terminate in semi-circular trunnion portions 24a, 34a, which, when the two beams are assembled, form hollow annular housings. Each of the beams 20a and 30a is traversed vertically by a plurality of registering apertures of comparatively large size which apertures receive a plurality of tie bolts 26a provided with nuts 28a which draw and hold them in assembled relation. The extreme ends of the beams are also bolted together by similar, though smaller, bolt and nut members 36a, 38a as shown. In all, six bolts 26a and four bolts 36a with an appropriate number of nuts 28a and 38a are utilized in fixing the upper and lower beams 20a, 30a in assembled relation.

By reference to FIGURES 21 and 25, it will be seen that when assembled the housings or ears 40a, 40b which project outwardly beyond the main tie bolts 26a to either side of the central portions of the beams 20a and 30a surround the assemblies 300a, 300b on either side. It may be seen that housings 40a, 40b are considerably larger than the outside diameter of the assemblies 300a, 300b. Remembering that both fixed and moveable gripping heads 200a and 100a must be locked in varying spaced relation onto the assemblies 300a, 300b, it will be seen that the medium for producing a releasable locking of the respective gripping heads is embodied within the housings 40a, 40b. Since each medium is the same, a description of that disclosed in FIGURES 19 and 25 should serve as an adequate description of all.

As indicated in FIGURE 19, the left-hand side of housing 40a is provided with an in-turned annular flange 42a. Against this flange 42a is disposed an annular bearing member 44a having a conical face 46a. Disposed against this surface 46a and rotatable with respect thereto is a lock nut 48a. This nut 48a has an internal diameter which closely approximates the outside diameter of tubular assembly section 300a and is also provided with a rib pattern 50a of a configuration complementing that provided on the exterior of the assembly 300a. Thus, this nut 48a forms with the tubular assembly 300a a so-called "breach block" type of locking arrangement wherein, as the locking nut is rotated only a partial turn in one direction, the thread-like ribs 50a will be engaged with those provided on the assembly while rotation through a partial turn in the opposite direction places the projecting ribs in registry with the smooth portions of the assembly disengaging the lock nut 48a from the ribs provided on the outer surface thereof. In order to lock the housing 40a and the gripping head 100a to the nut, a second bearing member 52a is provided, which bearing member 52a is also provided with a conical face 54a that is in engagement with a similar face 56a provided on the lock nut 48a. The bearing member 52a is fitted within the interior of housing 40a and held in place by a lock ring 58a, which engages an annular groove 60a located in the interior wall of the housing 40a. Thus, partial rotation of nut 48a or 48b as the case may be in either direction locks or unlocks either head assembly, whether it be fixed head 200a or moveable head 100a with respect to the tubular assemblies 300a, 300b.

In order to provide for rotation of the nuts 48a which, because of the breechblock type of locking action that occurs need only be partially turned to either of two positions, the top of housing 40a is provided with mounting pads 62a. As indicated in FIGURE 25 on these pads 62a, there is mounted a hydraulic motor assembly 70a. The cylinder barrel 72a of this assembly is pivotally affixed to pad 62a by pivotal mounting means 74a while the piston rod 77a is connected to the nut 48a through the medium of a projecting ear 76a bolted to nut 48a and projecting outwardly through a suitable slot 80a provided in the housing 40a. Thus, as indicated in FIGURE 25, if the hydraulic motor 70a is energized to move the connecting ear 76a downwardly, nut 48a will be rotated counter-clockwise and locked to tube-like assembly 300a while if the hydraulic motor 70a is energized to move the connecting ear 76a upwardly, thus rotating lock nut 48a clockwise, the nuts will be disengaged from the ribs provided on assemblies 300a, 300b, and the gripping head assemblies freed from the tube-like assemblies 300a, 300b.

Again considering the housings 40a, 40b, it will be seen that these housings also serve as supports for the gripping head assemblies 100a, 200a. To this end, a housing such as 40a is provided with a lower projecting mounting pad portion 82a. The bottom surface of this pad 83a is recessed slightly to receive a conventional spherical joint assembly 84a which in turn rests on a truck assembly 90a. The spherical joint assembly 84a as shown is comprised of a pair of pin connected washer-like members 85a having mating spherical surfaces and need not be described in greater detail except to say that a pin 86a affixed to truck assembly 90a extends only through lower washer 85a connected to truck assembly 90a and terminates just below the top of lower washer 85a so that truck assembly 90a can move due to any unevenness in the rails 4a slightly with respect to top washer 85a affixed to head 100a. The truck assembly 90a is simply a fabricated wheeled support provided with flanged wheels 92a engageable with the rails 4a, 4b and 5a, 5b as is believed obvious. Each of the gripping head assemblies is supplied with four such truck assemblies, there being eight such assemblies in all, all identical and all performing the function of supporting the gripping head assemblies on the rails whereby the gripping heads may move longitudinally in the pit area 10a. It will be apparent that, since each of the gripping head assemblies is so supported, there is no bending stress introduced into assemblies 300a, 300b. Thus, these assemblies are designed primarily to resist compression loads and because of this their wall thickness and diameter both are considerably less than would be the case if gripping head assemblies 100a, 200a were merely suspended therefrom, whereby these tubular assemblies would be subjected to severe bending loads.

During certain operations of the apparatus, it is essential that some means be provided whereby one or the other of the workpiece gripping heads must be locked in place at a given position along the length of the tracks 4a, 4b and 5a, 5b. To accomplish this, at least one pair of each of the two pairs of truck assemblies supporting each of the gripping heads 100a, 200a is provided with a hydraulically operated locking pin 94a, as may be clearly seen from an inspection of FIGURES 19 and 20. Each of these pins 94a may be selectively operated from a suitable source of hydraulic pressure in a manner to be described in connection with FIGURE 30. Each of these locking pins 94a when energized projects downwardly between the rails 4a, 4b and 5a, 5b and engages either drawbar member 6a or 6b of any suitable type. Preferably, the drawbar takes the form of an I-beam laid on its side. The webs of the drawbar beams 6a, 6b, are provided with a plurality of longitudinally spaced apertures 8a indicated schematically in FIGURE 19, which arrangement is carried out throughout their respective lengths. Obviously, then either one or both of the

two gripping head assemblies 100a, 200a may be locked to the drawbar 6a in any one of a plurality of positions throughout their lengths. A detailed description of the operation of the described arrangement will be deferred until the operation of the main and secondary hydraulic systems, disclosed in FIGURES 29 and 30, is described in detail.

Having thus far considered the assemblies 300a, 300b, the manner in which the gripping head assemblies 100a, 200a are releasably locked thereto as well as the manner in which the gripping head assemblies 100a, 200a may be selectively locked to the tubular assemblies in one of a plurality of positions along the rails 4a, 4b and 5a, 5b consideration will now be given to the manner in which a workpiece W is maneuvered and held in the gripping head assemblies 100a, 200a during a stretching operation.

Referring to FIGURES 21 and 22, it will be seen that the upper and lower beams 20a, 30a are so formed that a central slot S₄ is defined therebetween with the slot S₄ extending across the width of the head assemblies between the spaced tie bolts 26a on either side. Again, since all parts to be described are similar for both upper and lower beams, the letter designations "a" and "b" will indicate like parts. Referring to FIGURE 22, it may be seen that this slot S₄ is defined by upper and lower surfaces 102a, 102b which are substantially parallel and limit the maximum thickness of the workpiece W, shown in phantom outline, which can be introduced between the upper and lower beams 20a, 30a. The remaining portions of the opposing faces of the beam members with the exception of the mentioned surfaces 102a, 102b, are generally disposed in diverging relation as may be clearly seen in FIGURE 2. It will be further noted that the central portions 22a and 32a of the beam members 20a, 30a are in fact hollow box-beam sections and that they are tipped forward such that the greatest resistance to bending developed by these beams is not along a vertical axis but rather is at an angle to the vertical or, expressed another way, their major resistance against bending occurs along lines normal to the respective planes of the divergent surfaces 104a, 104b, respectively.

Each of the divergent surfaces 104a, 104b is covered by a respective removable guide and bearing plate 106a or 106b. Each of these plates 106a, 106b is provided with spaced guide ribs 108a, 108b wherein the spacing of the ribs 108a, 108b, corresponds to the width of each of a plurality of workpiece engaging wedge-shaped gripping jaws 110a, 110b. The ribs 108a, 108b also serve to lock the gripping jaws 110a, 110b in place on the bearing plates 106a, 106b, as will be apparent, and are preferably fixed thereon by removable fasteners such as bolts 112a, 112b. Though not shown in detail, it is believed that it can be readily understood that the ribs 108a, 108b may be provided with a top cap or other means bolted or otherwise removably fixed to their top surfaces. These caps would then engage slots (not shown) provided in each adjacent side of two jaws 110a, 110b to hold them in slideable engagement on the bearing plates 106a, 106b and yet prevent the jaws 110a, 110b from being displaced when a workpiece W is removed from the apparatus.

Each of the gripping jaws 110a, 110b is a wedge-shaped block having a configuration such that its workpiece engaging surfaces 114a or 114b are parallel to a plane extending medially of the slot S₄. Since the opposite face which engages the bearing plates is disposed at an angle to the workpiece engaging surfaces 114a, which angle is the same as the angle of the diverging faces 104a, 104b of the beams 20a, 30a it will be observed that as each of these jaws 110a, 110b moves forward and rearward the working surfaces 114a, 114b will always remain parallel but that the space between the upper gripping surfaces and lower gripping surfaces 114a, 114b of a pair of vertically opposed jaws increases or decreases depending on the direction of movement of these jaws. Thus, movement of the jaws serves to lock or release a workpiece W between

them and, additionally, it will be apparent that pull on the workpiece W tends to increase the gripping pressure between any two of opposing jaws. Thus, greater pull on workpiece W results in greater gripping forces on its ends. To increase the gripping efficiency of the workpiece engaging surfaces 114a, 114b of these jaws 110a, 110b, the jaws are provided with special hardened inserts 116a, 116b. Each of these inserts 116a, 116b not only increases the grip force between jaws 110a, 110b and workpiece W but also because of their hardness reduces wear that otherwise might render each of the jaws unusable in a short period of time. Preferably, the inserts are removable and suitable bolts 118a, 118b may be used to fix them to the surfaces 114a, 114b of the jaws 110a, 110b, as may be clearly seen in FIGURE 22.

Considering now the enlarged view of FIGURE 24 in conjunction with the showings of FIGURES 22 and 23, it may be seen that mounted on the rear of the beams are the mechanisms for actuating the gripping jaws 110a, 110b. The jaw-operating mechanisms 120a, 120b are all carried on a pair of L-shaped housings or manifolds 122a, 122b, one housing 122a being fixed to the upper beam 20a and the other housing 122b fixed in inverted position on the lower beam 30b. As may be clearly seen in both FIGURES 22 and 24, suitable lips 117a, 117b are provided on the rear faces of the beams 20a and 30b and recesses 119a, 119b are machined into the divergent surfaces 104a, 104b. Complementary slots 123a, 123b in one leg of the L-shaped housings 122a, 122b register with the slots 119a, 119b in such a manner that generally rectangular cross-sectioned keys 121a, 121b may fit in the rectangular recess defined by the slots 119a, 123a and 119b, 123b. The opposite legs of the housings 122a and 122b are provided with apertured ears 128a and 128b through which are passed bolts 129a and 129b, which in turn engage the top and bottom surfaces of the lips 117a, 117b, respectively. As these bolts are tightened, it will be apparent that the housings 122a and 122b will be clamped in position and locked to the beams 20a and 30a. In addition, a further series of bolts such as bolts 131a for housing 122b may be passed through the opposite legs of these housings 122a, 122b and into the divergent faces 104a, 104b of the beams 20a, 30a to further prevent displacement of the housings 122a, 122b from the beams.

Referring to the enlarged sectional view of FIGURE 24, it will be seen that these housings 122a, 122b define cylinder blocks in that each housing is provided with a series of cylinders 124a, 124b (only one being shown) in their generally horizontal leg portions, one for each of the gripping jaws 110a, 110b. The other leg of these L-shaped housings is also internally bored to define a plurality of cylinders 126a, 126b each one of which is in communication with the first-mentioned cylinders 124a, 124b, through elbow-like passages 125a, 125b, disposed within each of the cylinders 124a, 124b, as shown in FIGURE 24, is a piston assembly 130a. This piston assembly 130a is in the form of a barrel-type rod having one end 132a connected by pin 113a to an ear 111a provided on the rear of a gripping jaw 110a. Adjacent the opposite end of the barrel, there is provided an annular flange or rib 134a. Since the piston diameter is smaller than the diameter of cylinders 124a, 124b, it will be obvious that this annular flange 134a forms a working surface upon which hydraulic fluid may act. To this end, immediately behind this surface there is provided a series of annular oil seals 136a, 138a (FIGURE 24) which prevent leakage of fluid between flange 134a and the wall of cylinder 124a. It will be noted that one group of seals 136a is positioned to prevent leakage of fluid admitted in the annular space defined between the piston 130a and the cylinder wall to the left of the annular flange 134a while the second group of seals 138a surrounds a flanged collar 142a and is held in place by an end cap 140a which acts as a further piston and that these latter seals 138a are

disposed to prevent leakage of fluid which may be admitted to elbow-like chamber 125a through port 150a. The jaw end of cylinder 124a is also closed by a cap 144a and seals 146a which surround the barrel and prevent leakage from the cylinder. Obviously, then, as fluid is admitted on the left-hand side of the cylinder 124a through a suitable port (not shown), the piston assembly 130a will move to the right while fluid admitted to the chamber 125a through port 150a will cause piston assembly 130a to move to the left. Since the piston 130a is connected to a jaw 110a by pin 113a, the movement of the piston 130a will move the jaw in the same direction. It is obvious that should piston 130a move too far to the right, as seen in FIGURE 24, the seals 138a could hang up on the step formed between cylinder 124a and chamber 125a. To prevent this, cap 140a is provided with a projection-like stop 148a which will hit the end wall of the elbow-like chamber 125a and limit the travel of piston 130a to the right.

Each of the generally vertical cylindrical chambers 126a formed in the other leg of the housing 122a is provided with a piston. This piston 152a is generally cup-shaped and is provided with annular seals 154a. Since the upper end of the cylinder 126a is closed by cap 156a, a closed chamber is defined between piston 152a and end cap 156a, which chamber is supplied by a pneumatic source (not shown) through port 158a and defines the air end of a pneumatic accumulator. Normally, then, piston 152a will be positioned, as shown in FIGURE 24, during all normal operations.

The opposite or lower side of piston 152a ordinarily rests against a lip 160a of an annular valve body 162a which fits within an annular port 164a that is in communication with chamber 125a. This valve body 162a is parted laterally by a series of radial apertures 166a and includes a seat 170a. Spring biased against seat 170a by means of spring 168a is a cup-shaped poppet 172a. This poppet is also parted as at 176a and receives one end of spring 168a which has its other end resting against a seat 182a held in place by lock ring 184a. It will be seen that the ports 166a are ordinarily blocked by the cup-shaped poppet 172a. The entire assembly thus provides a pneumatic cushion for shock introduced through piston 130a with provision for slow return by means of oil metered through the check valve orifice.

Additionally, it will be seen from a review of FIGURES 22, 23 and 24 that the L-shaped housings 122a and 122b are provided with trunnions 190a, 190b extending from the generally vertical leg thereof. These trunnions carry rotatable shafts 192a, 192b provided at either end with gear segments 194a, 194b. The gear segments mesh in such a manner that rotary movement of each of the upper and lower shafts 192a, 192b is equal and opposite. The shafts 192a, 192b are connected by crank arms 196a, 196b to a plurality of strut cylinders 198a, 198b which in turn are connected to the rear of the gripping jaws 110a, 110b. These strut cylinders may be considered as solid links which connect pins 195a, 195b and 197a, 197b except that they are filled with oil having a slight compressibility and hence act as very stiff springs which deflect under pressure and allow some relative movement between the jaw segments 110a, 110b.

The described structure is a combined equalizer and shock absorber system for each of the jaws. However, since the operation thereof is tied in so intimately with the hydraulic system of FIGURE 30, a description of the operation thereof will be temporarily deferred until the FIGURES 29 and 30 are discussed in detail.

Returning now to the drawings and in particular FIGURE 21, it will be seen that this figure is a front or working face view of the gripping head assembly 100a and discloses, along with FIGURE 27, the ironing roll assemblies used to guide and flatten the end of a plate immediately prior to the time that the gripping jaws engage the work-

piece. Dependently attached to the beam 20a are a plurality of individual hydraulically actuated cylinders 452a. These cylinders are fixed to the sloping face of anchor beams by any suitable means preferably as by bolting or the like through a common mounting pad 454a. The mounting pad is reinforced by a series of vertically disposed gussets 456a. From the lower end of the cylinders 452a project piston rods 457a. The lower end of each piston rod 457a has attached thereto, as by screw threads and nuts or the like, a yoke assembly comprised of a horizontal plate 458a having depending ears 460a between which on suitable journals or trunnions are fixed rollers 462a. Thus, as seen in FIGURE 21, the upper leading or workpiece entering edge of the slot S₄ is defined by a plurality of generally coaxial, vertically movable, hydraulically actuated rollers 462a. Suitable means are provided to prevent twisting of these rolls about vertical axes as is conventional and described in connection with the apparatus of FIGURES 1-16. The rollers 462a are moved away from the workpiece W after positioning thereof in slot S₄.

The lower anchor beam 30a also is provided with a roller assembly 470a which rests upon and is fixed to the sloping face thereof. This assembly differs considerably in operation and structure from the top rollers 462a and, hence, warrants detailed treatment.

Again referring to FIGURES 21 and 27 in particular, it may be seen that bolted or otherwise fixed to the shoulder or shelf on beam 30a is a transversely elongated base plate 472a. Paralleling the central longitudinal axis of this base plate 472a in spaced coaxial relation thereon, there is provided a pair of ribs 474a, 474b. In slidable engagement with the base plate 472a and having slots registered on the ribs 474a, 474b is a pair of solid block members 476a, 476b having sloping upper surfaces 478a, 478b such that these blocks define wedges. Obviously, the blocks 476a, 476b are slidable toward and away from each other and are so disposed that the sloping surfaces 478a, 478b face toward each other. In order to move the wedges toward and away from each other and to obtain simultaneous equal and opposite movement of each of the blocks 476a, 476b, they are provided with a threaded aperture for receiving the opposite ends of a driven shaft 477a. The ends of the shaft 477a are threaded and conventionally the threads are of opposite pitch. In other words, as viewed in FIGURE 21, the right-hand end of shaft 477a is provided with a left-hand thread while the left-hand end is provided with a right-hand thread. The shaft 477a is connected to a reversible electric motor 480a by the usual pulley and belt drive 482a and is conventional. Thus, as the motor drives shaft 477a in one direction, the blocks 476a, 476b will be moved simultaneously and equally toward each other. If rotated in the opposite direction, the shaft 477a will cause similar movement of the wedges 476a, 476b away from each other.

Overlying the wedge and drive mechanism described immediately above is an elongated, transversely extending, channel-shaped carrier beam 484a. Preferably, this carrier channel is so disposed as to open downwardly. Disposed interiorly within the channel in the pocket defined by the web and flanges of the carrier beam 484a is a pair of additional wedge-shaped blocks 486a, 486b. These blocks 486a, 486b are provided with sloping bottom faces 488a, 488b. These faces rest on the sloping top faces 478a, 478b of the moveable blocks 476a, 476b and, obviously, as the latter are moved toward and away from each other, the carrier beam 484a will be moved upwardly and downwardly.

Mounted upon the upper face of the carrier beam 484a is a plurality of rollers 490a suitably journaled in suitable apertured brackets. These rollers are arranged in coaxial coterminous relation and, of course, will be carried upwardly and downwardly in response to similar movement of the carrier beam. It might be well to note that the ends of the carrier beam 484a are provided

with vertically disposed plates 492a, 492b which ride in vertical slots (not shown) provided in the face of the anchor beam 30a to assure that movement thereof will be truly vertical and further to maintain the carrier in proper position.

Because of the fact that the friction between the sloping surfaces 478a, 478b and 488a, 488b, respectively, is considerable and, further, due to the fact that the friction between the threaded shaft 477a and the blocks 476a, 476b is considerable, it will be apparent that once the rollers 490a are set at a selected vertical position they will remain fixed so long as the motor 480a is not energized. Preferably, the rollers 490a are always adjusted such that the upper planar surface defined by their periphery is always disposed below an imaginary planar surface passing through the slot S₄ exactly one-half of the dimensional thickness of the plate or workpiece W being stretched. The purpose of this arrangement is to assure that, as the cylinders 452a are actuated to bring holdown rollers 462a in contact with the workpiece W, the workpiece will be aligned as nearly as possible with a plane extending medially through the slot S₄. Thus, the wedge-like gripping members 110a, 110b will grip the top and bottom surfaces of the workpiece W at approximately the same distance from its end and no off-center loading is created in the workpiece by these latter members.

Referring briefly to FIGURE 27, a further aid to the maneuvering of workpieces into position in slot S₄ is disclosed such as an auxiliary positioning roll assembly. While this equipment would ordinarily appear in the face view of FIGURE 21, it is not shown in order that details of the ironing roller assemblies 462a and 470a could be shown in detail.

The auxiliary positioning roll assembly consists of two box-beam supports 494a mounted on the beam assembly 30a and the supports for plate 472a. These beams are positioned directly in the center of each of the gripping head assemblies 100a, 200a on lower beams 30a, 30b only and are bisected by the centerline of the apparatus. To these supports 494a is rigidly fixed a hydraulic motor 496a. To the piston rod of the motor 496a is fixed a yoke 498a carrying two rollers 499a. These rollers 499a are spaced equidistantly apart from the piston rod of motor 496a and are raised and lowered thereby to help position a workpiece on ironing rolls 490a.

Prior to describing the over-all operation of the apparatus, consideration must be given to the sequence control valve 700a as shown in FIGURE 28. Since this valve is an essential part of the main hydraulic system shown in FIGURE 29, it is essential that its construction and mode of operation be clearly understood.

As is apparent in both FIGURES 19 and 29, this sequence valve is housed in the extreme end of a stationary manipulating rod 400a, which is suitably ported as will be subsequently more apparent, to provide passages communicating with the inlet and outlet ports of the valve. By locating the valve assembly 700a in the end of manipulating rod 400a, it is apparent that removal of the valve for servicing or repair is facilitated. It will be noted that all components utilized in the valve assembly are concentric and, hence, such concentric arrangement will be understood, though not specifically alluded to as such, in the description to follow.

It will be apparent from an inspection of FIGURE 28 that the manipulating rod assembly 400a is hollow, being provided with a central passage 412a. This passage is enlarged at the extreme left-hand end of the rod into stepped cylindrical chambers 404a, 406a. The manipulating valve assembly 700a rests in the area embraced by these chambers. The end of the rod is closed by a cover 408a bolted or otherwise fixed in leakproof relation thereto and provided with at least one pair of ports 410a, 411a in communication with the larger chamber or passage 406a. The other chamber or passage 404a

is also in communication with a port 414a which is drilled in the rod 400a in the form of an annular recess in the cylinder wall.

It will also be noted that the rod 400a is further provided with passages 416a and 418a which run axially of its length, and a smaller passage 422a. These passages as well as port 414a are all in communication with the anchoring manifold 420a which includes three separate chambers 421a, 423a and 424a, as schematically indicated in FIGURE 29. The purpose of this arrangement will subsequently become apparent. As seen in the drawing the sequence valve assembly 700a is housed within rod 400a fixed to the manipulating piston head by bolts or equivalent fastening means.

Valve assembly 700a further includes a hollow ported valve body 715a having a port 716a communicating with chamber 406a, a radial port 714a in communication with port 414a, and an external line 425a indicated schematically. The valve body also is provided with a small diameter axial port 721a in communication with a spring-biased check valve 723a and also with a similar though smaller valve 725a. Still another port 727a is provided having one end communicating with the hollow interior of the valve body 715a and its other end in communication with a port 422a provided in the manipulating piston rod 400a, this port having a restricted orifice 731a.

Within and axially moveable with respect to the valve body 715a is a cylindrical valve spool 730a. This spool includes a central disc 733a provided with an aperture 735a and orifice 737a. From disc 733a extend skirts 739a, 741a, the former being provided with a port 745a. The valve spool 730a is connected to a pilot piston 750a. The pilot piston 750a includes an enlarged head 751a, provided with the usual seals, which rides in a longitudinal cylinder 754a suitably fixed within the valve body 715a. The pilot piston 750a further includes a rod 756a formed integrally with the head 751a and also an annular shoulder 758a and a threaded end receiving a nut 760a. The area of the rod 756a is such that the ratio of areas of the two sides of the piston 750a which are exposed to hydraulic pressure is two to one. In other words, using the the usual calculations, there is twice as much force exerted on the head end of pilot piston 750a as can be exerted on the rod end thereof.

The head end of pilot cylinder 754a is in communication with a passage 757a in turn communicating with check valve 723a. The rod end of this same cylinder is in communication through port 764a with previously described passage 727a.

As has been set forth above, the pilot rod 756a is provided with an annular shoulder 758a and a reduced threaded end for nut 760a. The reduced end of pilot rod 756a is inserted within the aperture 735a in the central disc portion 733a of the valve spool 730a and is slidable with respect thereto. The nut 760a is applied to its threaded end and also engages the disc 733a, while shoulder 758a engages the disc 733a from the opposite side. Since the reduced portion of the pilot rod 756a is of such a longitudinal length as to space the nut 760a and the shoulder 758a some distance apart, it will be apparent that the spool 730a may move relative to the pilot piston 750a and vice versa.

Surrounding the pilot cylinder 754a and slidable longitudinally therewith is a cup-shaped spring-biased stop member 784a. This member is provided with an in-turned annular flange 776a adapted to engage an out-turned annular flange 768a provided on the end of pilot cylinder 754a, such that the cup-shaped stop member 784a may not slip off the end of pilot cylinder 754a. A suitable coil spring 770a circumscribes the pilot cylinder 754a and bears against a shoulder 772a and also against an out-turned peripheral lip 774a provided on the cup-shaped stop member 784a to bias this member such that flanges 776a and 768a are in contact.

Having thus far described the overall apparatus, detailed consideration will now be given to the mode of operation of the apparatus, as well as the external hydraulic components which enable its operation. Accordingly, by referring to FIGURES 29 and 30, it may be seen that there is disclosed the main hydraulic system in schematic form. Also, in reduced size, there is included a schematic section of one of the tubular assemblies previously described. Since the operation of each assembly 300a, 300b is identical, only one assembly 300a is shown, it being appreciated that assembly 300b would be similarly operated.

It will be assumed, in order to establish a starting point in a cycle of operation, that a workpiece W is already in position, gripped by the gripping heads 100a, 200a, and that a stretching operation is to begin. Referring to FIGURE 29, it will be seen that the entire system is controlled by a single lever H and further that movement of the operator-operated lever to the right moves moveable gripping head 100a to the right while movement of the lever to the left causes it to move to the left. Also, it will be assumed that dead center is a neutral position. The operator, therefore, will move the lever H to the left to start stretching. Hydraulic fluid supplied under pressure from pumps P₁ and P₂ will then pass out of the pumps P₁ and P₂ through lines 501a and 510a to line 502a into the chamber 424a of the manifold 420a. From chamber 424a, the fluid will pass into the port 714a of the sequence valve (FIGURE 28). Since this port is blocked by the position of valve spool 730a, the fluid cannot enter the hollow interior 412a of the manipulating rod 400a. However, since chamber 421a of manifold 420a is in communication with line 502a, fluid will pass through this chamber and into passage 416a in manipulating rod 400a and thence into the left-hand side of the manipulating cylinder through the port 503a. At the same time, fluid will exhaust from the right-hand side of the manipulating cylinder through port 504a, passage 418a, chamber 423a of manifold 420a, lines 505a and 506a to the pump P₁. Because the housing 304a is 40 moveable with respect to manipulating rod 400a, it will be seen that the entire assembly, including moveable gripping head 100a will begin to move toward the left. This movement continues until the maximum force that can be exerted by the manipulating cylinder is attained. Preferably, this maximum occurs at a pressure of 2500 p.s.i.

It will be noted that as the housing 304a moves to the left the annular shoulder 305a thereof moves away from the annular shoulder 335a provided on the main stretching piston 325a. The reason for this will be obvious as the description proceeds.

Meanwhile, the pressure is also building up in sequence valve 700a as fluid in passage 721a acts on the ball check valve 725a. Since this valve is set to open at 2500 p.s.i., when this pressure is reached it moves from its seat to admit fluid into passage 757a and into the head end of the cylinder 754a where pressure is exerted on the head end of piston 750a. This piston begins to move forcing fluid from the rod end of cylinder 754a through passage 727a and restricted orifice 731a into passage 422a and eventually into passage 518a and to the intake side of pump P₁.

The rate of movement of piston 750a is, of course, determined by the rate of exhaust of fluid through orifice 731a which acts to prevent too violent and sudden action thereof.

As piston 750a continues to move, shoulder 758a eventually strikes the central web 733a of valve spool 730a pushing it to the right, as viewed in FIGURE 28, to align ports 414a, 714a and 745a. In so doing, fluid is admitted into the hollow interior 412a of manipulating rod 400a and passes therethrough and to ports 323a where it begins to exert pressure in stretching cylinder 320a against piston 325a.

It will be seen, then, that as the pressure builds up in stretching cylinder 320a, the piston 325a will begin to move to the left until shoulder 305a again abuts shoulder 335a on the end of the moveable tubular portion 304a. As soon as this occurs, pressure builds up rapidly in this cylinder. Since the diameter of this piston and cylinder is so much greater than that of the manipulating cylinder and its associated piston 402a, it will be seen that the force exerted by shoulder 305a against shoulder 335a is much greater than that developed in the manipulating motor and that it is added to the load being imposed on the workpiece W.

Since fixed head 200a is locked to one side of the tubular assembly and is immobile and gripping head 100a is locked to the moveable tubular support section, it is obvious the workpiece W will be put under increasing tension until it begins to stretch or yield in tension. All of the equal and opposite loads are then created in the tubular assemblies between the two gripping heads and, further, since the workpiece W lies in the same plane as that in which the center line of the assemblies 300a, 300b lie, there are no eccentric loads imposed on any of the components making up the apparatus.

By measuring the actual distance the moveable head moves during the stretching, the amount of stretch in the workpiece W may be readily determined. When the desired stretch occurs, the stretching cycle is complete.

A supercharge or booster pump P_b driven by motor M₃ is used to supply fluid to the inlet side of the pumps P₁, P₂, P_{1a} and P_{2b}, which latter pumps are capable of building up a pressure of 6000 p.s.i. in the system. The booster supplies fluid through lines 507a, 508a and check valve 536a to what is then the inlet side of the pumps P₁, P₂, which are connected in parallel. This supply of fluid supplements that which has been exhausted from the left side of the manipulating cylinder through passage 418a, chamber 423a and line 505a. The ultimate pressure developed during stretching is 6000 p.s.i.

Upon completion of the stretching phase of the operating cycle, the control lever H is moved from its left-hand position L through center to an intermediate right-hand position R₁. The purpose of this intermediate position is to cause decompression of the fluid which is under 6000 p.s.i. pressure. Movement of this lever to the full right-hand position R₂ is prevented by means of an electrical interlock consisting of a pressure switch PRSW placed in series with a suitable limit switch LS to block the movement of lever H until the pressure drops below the preset of the switch PRSW.

With the handle in the R₁ position, the pumps P₁, P₂ are reversed. Fluid, then, will flow out of the stretching cylinder 320a, through ports 323a and through the manipulating rod 400a and at the same time out of the left-hand side of manipulating rod or cylinder 400a to the pumps P₁, P₂ since the exhaust ends of these pumps now become the suction ends. At the same time the pumps are reversed, pressure is put on line 505a to chamber 423a, passage 418a and into the right-hand side of the manipulating cylinder 400a through port 504a.

Referring to the sequence valve 700a, shown in FIGURE 28, it will be seen that, as pressure is applied against the right-hand side of piston 402a, the fluid on the left-hand side thereof will be under pressure as the housing 304a begins to move to the right and also begins to move the stretching piston 325a back into cylinder barrel 322a causing the fluid therein to build up pressure in the interior of the rod 400a. This fluid then acts against sequence valve spool 730a to cause it to move to the left, while at the same time fluid from the head end of the pilot cylinder 754a passes through passage 757a and ball check valve 723a, lifting it from its seat into passage 721a and thence to the pumps until the ports 745a, 714a and 414a are again out of alignment and port 414a is again blocked.

It will be noted that the rate and time of action of the sequence valve spool is a function first of the size of ball check valve orifice and further that this valve cannot move solely by the pressure against spool 730a since the central portion of the spool is drilled to form a port 737a and is hydraulically balanced. Rather, the fluid pressure acts against shoulder 758a and through passage 764a against the piston 750a. Since the areas of the head and rod side of the pilot piston 750a are arranged at a 2 to 1 ratio, it is only when the pressure drops, due to decompression, on the head end of this piston such that the force exerted on the rod end thereof overcomes this decreasing pressure that the spool 730a is moved back to the position in which it is shown in FIGURE 28. The entire apparatus is now stabilized and it is necessary to remove the stretched workpiece from the stationary gripping head 200a.

To accomplish this, the jaws of head 200a are released, as will be described, and the lever H is again moved to the full left-hand L position.

Again, the pumps are reversed and fluid flows in the manner described into the right-hand side of the manipulating cylinder causing the tubular assembly section or sleeve 304a and head 100a to continue to move to the left. This drags the workpiece W free of the fixed head 200a. It will be noted that the pressure required to move the moveable head 100a when a workpiece is not clamped in the two gripping heads is considerably less than that which actuates sequence pilot piston 750a and that valve spool 730a remains exactly as shown in FIGURE 28, and stretching cylinder 320a is not affected. Normally, after the workpiece W is freed from head 200a and also released from moveable gripping head 100a, the stretcher is at rest. As in the case of all hydraulic equipment, some creeping of the moveable head 100a might occur. Accordingly, the two pressure relief valves 520a, 530a connected to line 508a, whose function will be explained more fully hereinafter, are vented by means of the spring-closed, solenoid-opened vent valves 532a, 534a, which exhaust into the reservoir R.

Returning now to the pressure relief valves 520a, 530a, it will be seen that these valves are both connected into line 508a, which also includes a pair of ball check valves 509a and 536a. The line 508a is, in effect, a by-pass line extending across the pumps between line 505a and line 510a. The pressure relief valve 520a is set for a pressure of 6000 p.s.i. while valve 530a is set for 3000 p.s.i. It will be seen that valve 520a will relieve the pressure in line 510a through line 521a to line 508a should the pressure therein suddenly exceed 6000 p.s.i. Relief valve 530a will relieve pressure in line 505a if the pressure in this line exceeds 3000 p.s.i. through line 531a and to line 508a. Check valves 509a and 536a both open at 6000 p.s.i. whereby they will act to admit fluid from booster pump P_b only on demand.

A third relief valve 540a is provided in line 508a. This valve is solely for the protection of the supercharge or booster pump circuit since line 507a connects directly into line 508a. The valve 540a exhausts to the reservoir R should the pressure in the system exceed 6000 p.s.i. in contrast to valves 520a and 530a which open to recirculate fluid in the system.

The stretcher being at rest, the gripping jaws of moveable head 100a are released and a new plate lowered into position and gripped by moveable head 100a.

The control lever H is then moved to the right. Since the system is at idle, the pressure switch PRSW is no longer active in maintaining limit switch LS in blocking condition. Accordingly, lever H will move to the full right-hand position R₂. The pumps P₁, P₂ are again energized to pump through lines 506a, 505a, chamber 423a and passage 418a to the right side of the manipulating motor. The left-hand side of the manipulating motor is again exhausting so that the cylinder formed from the section 304a and the moveable head 100a again move to-

ward fixed head 200a. In so doing, the annular shoulder 305a will again fully abut shoulder 335a and the stretching piston 325a is pushed toward the plug end of cylinder barrel 322a. Since the stretching cylinder is still filled with decompressed fluid, it will be seen that some means must be provided to exhaust this fluid fully to enable movement of the piston 325a. This is accomplished again through sequence valve 700a.

Remembering that the hollow rod 400a is the means of communication with the stretching cylinder 320a, it will be seen that the fluid in this rod will be pressurized. Referring to FIGURE 28, it will also be seen that the sequence valve spool is in the position shown and that this pressure will act against spool 730a causing it to move against spring 770a. As spring 770a compresses, the port 745a will eventually line up with port 716a and fluid will pass into passage 406a and eventually through ports 410a, 411a in closure member 408a to the reservoir R.

When the end of workpiece W is finally positioned in fixed head 200a, the lever H is returned to center. Since there is no longer any movement of the stretching motor piston 325a, all fluid pressure on sequence valve spool is relieved and the spring 770a again returns the spool to the position shown in FIGURE 28 and all ports are blocked. A new stretching phase of the operation begins as soon as the lever H is again moved to the position L.

Having described the general operation of the main hydraulic equipment, consideration will be given to certain features thereof which assure safety if a workpiece should break. To this end, it will be noted that both chambers 421a and 423a of manifold 420a are in communication with a relief valve 550a through lines 554a and 552a. This valve is so connected that any undue pressure on the left side of the manipulating piston 402a will be bled from this side, i.e., chamber 421a, through the valve 550a and to the right side of the piston 402a through chamber 423a. This valve acts in conjunction with a further safety device 360a which acts to absorb shock loads imposed at breakage.

When a workpiece W breaks, gripping head 100a tends to accelerate to the left and gripping head 200a to the right. The valve 550a allows restricted relative motion between gripping heads 100a, 200a, the energy being absorbed by the oil passing from one side to the other of piston 402a and by heat. The entire system is resiliently fixed to earth in the following fashion.

The right-and ends of the assemblies 300a, 300b are attached to pit wall 7a by means of a pair of identical shock absorber devices 360a, 360b through couplings 352a and piston rods 362a. As shown in FIGURE 26, the piston rod 362a is formed integrally with a piston 364a which is slidably within a cylinder 368a. As shown in FIGURES 17 and 18, the cylinder 368a is anchored to the pit wall by any suitable means. A closure member 370a through which the connecting rod 362a passes forms the remainder of the cylinder assembly.

Referring back to FIGURE 29, it may be seen that one end, the head end of cylinder 368a, is provided with ports 372a in communication with a gas bottle (not shown) through a reducing check valve 369a (shown schematically) of conventional form. The gas bottle is charged with an inert gas under pressure and the head end of cylinder 368a is filled with pressurized inert gas pushing piston 364a toward the left under all normal conditions.

The closure member 370a is provided with an internal chamber 366a. This chamber 366a is in communication with an air-over-water accumulator 374a. In communication with this chamber 366a and the interior of cylinder 368a are a plurality of interspaced ports 375a, 376a. Ports 376a (only one being shown) comprise small diameter bleed holes leading to the interior of cylinder 368a, while the ports 375a (also only one shown)

normally closed by lightly biased poppet valves 377a are also in communication with the cylinder interior. Each of the valves 377a is comprised of a seat 379a, a stem 381a and a guide 383a. The end of the stem 381a is provided with nuts 385a. Circumscribing the stem and bearing against both the guide 383a and the nuts 385a is a valve biasing spring 384a which keeps the valve head 379a seated against the annular wall defining port 375a with a very light seating pressure.

During all normal operations of the stretching apparatus, the piston 364a, as shown in FIGURE 26, has been pushed toward the rod end of the cylinder 368a by the pressure of the gas entering ports 372a. The small volume of the cylinder 368a to the left of the piston 364a will also be filled with water from chamber 374a which has bled through the drilled ports 376a. However, when a workpiece fractures, assembly 300a and head 200a jerk to the right whereby the piston rod 362a and hence piston 364a will be driven toward the pit wall 7a. This compresses the gas on the head side of cylinder 368a and piston 364a may move toward the head end. The compression of the gas in the cylinder 368a generates a great deal of heat which is dissipated to the air through the metal cylinder 368a. Again, the conversion of energy from one form to another acts to absorb shock. Since the gas acting on the head end of piston 364a is under pressure, it will be apparent that, unless some means is provided to absorb rebound shock as the gas in the head end of piston 364a again exerts pressure thereon, there will be considerable rebound of the piston 364a with great shock being transmitted back to the tubular assemblies 300a, 300b. This rebound shock is controlled by the valves 377a and bleed ports 376a. Ordinarily, the normal position of valves 377a in seating relation with respect to the ports 375a is such as to close these ports and thus fluid acting through chamber 374a will be retained therein, except for that which has passed through ports 376a. However, when the piston 364a is driven to the right, as viewed in FIGURE 26, by the tremendous force produced as a result of breakage of a workpiece, the lightly biased poppet valves 377a are snapped open and, thus, the rod side of cylinder 368a will be filled with water drawn from chamber 374a and the source of fluid connected thereto through both ports 375a and 376a. Thus, the piston cannot fly back to its normal position because of the fact that the hydraulic fluid thus admitted to the rod side of the piston is incompressible and, further, due to the fact that as soon as pressure is exerted thereon the inlet poppet valves 377a again close blocking ports 375a.

However, since the ports 376a are open, the fluid drawn into the rod end of cylinder 368a will be gradually bled through these ports back into the chamber 374a. By proper selection of size or calibration, then, the normal rebound of piston 364a may be so controlled as to be reduced to a quick, yet acceptable, deceleration action as the gas expands additional energy against the piston 364a to return it against the gradually bled-out fluid until the piston 364a returns to its normal "at rest" condition, as shown in FIGURE 26.

It will be appreciated that since the rod 362a is connected to a stretcher tubular assembly 300a, as has been described, this snubber not only serves to absorb shock produced by breakage of a workpiece during stretching but further acts in the reorientation of the assemblies 300a, 300b and the stretcher head assembly 200a, which also is returned to its normal position.

Another feature included in the main hydraulic system of FIGURE 29 is a novel equalizer device which is used to coordinate movement between assemblies 300a, 300b during the stretching operation.

Considering now both FIGURES 29 and 31, it may be seen that means are provided which act between the two stretcher tubular assemblies 300a, 300b whereby equalized

movement is assured. Such an arrangement is shown schematically in FIGURE 29 and in detail in FIGURE 31.

In its simplest form and as shown schematically in both drawings, the coordinating apparatus may comprise a pair of drums 580a, 580b suitably mounted in the pit area 10 between the two assemblies. Cables 556a, 556b are passed around the drums 580a, 580b and each is fixed at one end in some suitable manner to the supporting truck means 330a. Preferably, the drums 580a, 580b are a self-reeling type; that is, some means is provided whereby the drums are always biased to cause the cables 556a, 556b to be under tension, tending to reel the cables upon the drums 580a, 580b. Such devices are well-known and need not be described in detail. Thus, if either end of truck means 330a is displaced more than the other, the displacement causes a corresponding relative angular displacement of cable drums 580a, 580b. As indicated schematically in FIGURE 31, these two drums are connected by means of shafts 551a, 551b to a suitable differential mechanism 570a. It will also be apparent from an inspection of FIGURE 31 that the cables 556a, 556b will be reeled and unreeled upon the drums in opposite directions. Shafts 551a, 551b are thus caused to rotate in opposite directions. Thus, the small bevel gears 752a, 752b carried on the inner ends of shafts 551a, 551b will be caused to rotate at the same rate of speed but in opposite directions. In mesh with and disposed between bevel gears 752a, 752b are a group of two or more (two being shown) carrier gears 561a, 561b. These gears are so called because they are mounted upon and carried by a differential carrier 559a, which is in turn fixed to and rotatable with a large ring gear 755a.

So long as the rates of rotation of the respective drums 580a, 580b and gears 752a, 752b are equal and opposite, it may be seen that the small carrier gears will rotate and, since the rotational forces acting thereon are equal and opposite, their axes will remain fixed, i.e., no rotational forces will act on the carriers 561a, 561b and ring gear 755a which would cause rotation thereof. The carrier gears are then merely idling.

However, should one or the other of the drums 580a, 580b be rotated at a faster rate than the other, unbalanced rotational forces are created which act on the carrier gears causing them not only to continue rotation but also to transmit a rotational load on the carrier such that the carrier gears 561a, 561b, as well as ring gear 755a are caused to rotate. Since the ring gear is in mesh with a small pinion gear 763a which rotates about a fixed axis, the rotation of the ring gear is imparted thereto. Obviously, depending on the relative rates of rotation of the bevel gears 752a, 752b, the direction of rotation of the ring gear 755a and, hence, pinion 763a may be one way or the other. The pinion 763a is connected to any type of gear drive which will cause this rotation to be converted into a reciprocating motion. This device is schematically illustrated in FIGURE 29 as being connected to valves V₁ and V₂ which operate to open and close these valves. The valves V₁ and V₂ are simple vent valves which may, when opened, bleed pressure from either lines 505a or 510a, as the case may be.

Thus, if one side or the other of the apparatus, i.e., either assembly 300a or 300b, begins to move faster than the other, as will ordinarily be the case due to the impossibility of absolutely synchronizing pumps P₁, P₂ and P_{1a}, P_{2b}, this movement will be converted by the differential mechanism 570a into action of the appropriate valve V₁ or V₂ to bleed off pressure in the faster moving assembly.

The stretching, loading and unloading operation having been described, consideration will now be given to the manner in which the distance between the two gripping heads 100a, 200a may be varied to accommodate work-pieces, i.e., plates, of various lengths.

It will be remembered that fixed gripping head 200a and moveable gripping head 100a are releasably locked to

the exteriors of the stationary and moveable portions of the assemblies 300a, 300b by the releasable lock nuts 48a and that each of the head supporting trucks 90a and 90b is provided with a drawbar engaging lock pin 94a which is retractable. When it is desired to move the gripping head 100a along the assemblies 300a, 300b, both gripping heads 100a, 200a are locked to the assemblies 300a, 300b. When the control lever H is moved to the left-hand position admitting oil to the left-hand side of the manipulating cylinder 304a, the moveable head 100a moves away from fixed head 200a. The breech block-type lock nuts of moveable head assembly are 100a are then rotated to unlock this gripping head 100a from the assemblies 300a, 300b at the same time the drawbar lock pin 94a carried on the trucks 90a for head assembly 100a is caused to engage drawbar 6a. The handle H is then moved to the right, thus sliding the moveable cylinders 304a to the right. Since the gripping head 100a is not locked to the tubular assemblies 300a, 300b and is locked to the drawbar 6a, it will be apparent that the position on the tubular assemblies 300a, 300b at which the gripping tubular support head 100a may be locked is changed because during movement of head 100a, although head 200a is not locked to the drawbar 6a, it is locked to the assemblies 300a and 300b. It will be noted that, as shown in FIGURES 17, 18 and 19, the cylinder sections 304a, 304b are provided with spaced areas of ribs 312a, 312b, 314a, 314b and 316a, 316b. As soon as one of these portions is properly lined up with the housings 40a, 40a of head 100a, the lock nuts 48a and 48b are again rotated to tubular assembly engaging position. The described operation would be carried out, for example, simply by moving the gripping head 100a from its minimum position relative to the fixed head 200a, as shown in FIGURE 19, to its maximum position, as shown in FIGURE 17.

In moving the gripping head 100a closer to fixed head 200a, the process is repeated in reverse. That is, the gripping head 100a is first carried inwardly as the assemblies 300a, 300b are contracted, locked to the drawbars, and then unlocked from the assemblies 300a, 300b, which are then expanded to the desired position, at which time the gripping head is released from the drawbars and again locked to the assemblies.

Similarly, the fixed head 200a may be adjusted along the length of the assemblies 300a, 300b. To carry out this operation, the procedure outlined above is followed but one further step is also included. In this case, the two heads 100a, 200a are locked to the assemblies 300a, 300b. The moveable head is moved by energization of the manipulating cylinder. The fixed head 200a is now unlocked from the assemblies 300a, 300b and its lock pins 94a are engaged with the drawbars 6a, 6b. The moveable head 100a is then again moved by energization of the manipulating cylinder. Since head 100a is locked to the drawbars 6a, 6b, these drawbars will slide between the tracks, and, since the fixed head 200a is also locked thereto, it will be moved to a new position along the fixed tubular portion 316a, as drawbars 6a and 6b are moved. The process is repeated until the fixed head 200a is properly located. Head 200a is then locked to the assemblies 300a, 300b and released from drawbars 6a, 6b. After the moveable head 100a is positioned, as in accordance with the steps outlined above, locked to the tubular assemblies and unlocked from the drawbars, the apparatus is ready to work on a workpiece of the desired dimension.

It will be appreciated, of course, that during the described positioning operation there is no workpiece W in the apparatus.

Having thus far described details of the structure and overall operation of the stretching apparatus, consideration will now be given to the operation of the gripping jaws, the drawbar lock pins, the lock nuts and the hydraulic circuit utilized in the operation of these instrumentalities. This circuitry is illustrated schematically in

FIGURE 30 along with schematic illustrations of the various operating components previously described.

The entire system is powered by a pair of pumps P₄ and P₅ driven by an electric motor M. The pump inlets are provided with strainers S₁ and S₂ and draw hydraulic fluid from a common reservoir R. Pump P₄ supplies fluid to the system through line 801a. To this line 801a is connected a pressure relief valve 802a normally biased to a closed position but set to open at a preselected pressure to exhaust fluid into reservoir R. Also connected to line 801a is a pressure gauge 803a through a stop cock 804a.

Pump P₅ energizes the system through line 805a and this line is also provided with a pressure relief valve 806a which is normally biased to a closed position at a pre-selected pressure. This valve 806a, however, also can be unloaded through a solenoid-operated, normally open dump valve 807a. Both relief valve 806a and dump valve 807a, when opened, exhaust directly to reservoir R. The line 805a is also provided with a pressure gauge 809a operating through stop cock 811a.

Pump P₄ is the main operating pump for the drag bar lock pin cylinders 93a, the workpiece positioning rolls 499a, the hydraulic motor assemblies 70a, 70b for lock nuts 48a, 48b and the clamping cylinders 452a, as well as the jaw-operating mechanisms illustrated as manifolds 122a, 122b. Pump P₅ is in the nature of a high volume, low pressure pump used to move the jaw mechanisms and the plate clamping mechanisms at a fast rate but with comparatively low force during all operations except actual clamping and stretching. Preferably pump P₄ is capable of developing 2500 p.s.i. at a rate of 20 gallons per minute, while pump P₅ can develop only 100 p.s.i. but at a rate of 120 gallons per minute.

Pump P₄ delivers fluid through line 801a to a common line 812a through a pressure reducing valve 810a. This valve is set to reduce the pressure in line 812a to a maximum of 1500 p.s.i. and does so by venting to reservoir R. Line 812a is considered a common line in that it is connected to each instrumentality. Therefore, to render the control system more readily understandable, consideration will initially be given to the more simply operated equipment.

It will be seen that line 812a is connected to the drag bar lock pin cylinders 93a through a one-way check valve 813a, a two-way spring-biased solenoid reversed valve 814a and line 815a to the rod or retract ends of the cylinders. The opposite or head ends of the cylinders 93a are in turn connected to a common return line 816a also connected to valve 814a. When in a normal de-energized position, valve 814a places line 815a in communication with line 812a through check valve 813a and line 816a in communication with reservoir R. Therefore, fluid from the pump P₄ will cause the pistons 95a to move toward the head ends of cylinders 93a, thus keeping the drag bar lock pins 94a in retracted position. The check valve 813a acts simply to close line 815a when either the pump P₄ is de-energized or when the output drain on this pump is being directed to a further instrumentality.

When it is desired to energize the lock pin cylinders to lock the pins 94a to drag bars 6a, 6b in carrying out the gripping head positioning operation previously described, the solenoid of valve 814a is operated. In so doing, the valve reverses, placing line 812a in communication with line 816a and line 815a in communication with reservoir R. Thus, the rod end of the cylinders 93a are exhausted to the reservoir while the head end is energized to move the pistons 95a and lock pins 94a downwardly and, as is obvious, into engagement with the drag bars 6a 6b.

Similarly, the two-positioned lock nuts 48a and 48b are energized from pump P₄. In this case, the fluid under pressure in line 812a passes to check valve 817a, then through the two-position solenoid reversed valve 818a and line 819a to the head ends of the lock nut operating motors 70a, 70b. Meanwhile, the rod ends of these motors

70a, 70b. Meanwhile, the rod ends of these motors 70a, 70b are exhausted through line 821a to the reservoir R.

When it is desired to unlock the heads 100a, 200a from the column assemblies 300a, 300b, the solenoid reversed valve 818a is energized and line 819a exhausts through the valve to reservoir R while line 821a is placed in communication with the line 812a through check valve 817a. This causes the rod ends of the lock nut cylinders 70a, 70b to be pressurized, rotating the lock nuts 48a and 48b as the head ends of these cylinders are exhausted to reservoir R.

Again, the function of check valve 817a is to prevent pressure drop in the system when the total capacity of the pump P₄ is being used elsewhere in the system.

Next, considering the workpiece lift roll motors 496a, it will be seen that since these rolls 499a must be "jockeyed," i.e., moveable to any one of a multiplicity of raised or lowered positions, to facilitate positioning of a workpiece W in the slot S₄ of the gripping head assemblies, the energization of these motors is somewhat different. To this end, line 812a is in communication with one-way check valve 823a. The valve 823a is connected to a three-position solenoid-operated valve 825a and this valve is in turn connected by line 827a to the rod end of the positioning roll motor 496a and by line 829a with the head end of this motor. The valve 825a also is in communication with reservoir R.

As shown in FIGURE 30, when the solenoids C and D of valve 825a are not energized, the valve is blocked, that is, all lines entering this valve are blocked so that no fluid can flow. When a plate is being loaded, however, it becomes desirable to jockey the positioning rolls 499a up or down. To lower the rolls 499a, solenoid D is energized. Valve 825a then acts to place line 812a and check valve 823a in communication with line 827a and line 829a in communication with reservoir R. As a result, the rod end of the motor 496a is pressurized while the head end exhausts through line 827a and valve 825a to reservoir R. The rolls 499a, yoke 498a, etc., move down. When the proper position is reached, solenoid D is de-energized and valve 825a again returns to de-energized condition, blocking all lines.

When it is desired to raise the positioning rolls 499a, the left-hand solenoid C is energized. Valve 825a then acts to place line 827a in communication with reservoir R whereby the rod end of motor 496a is at exhaust while at the same time line 829a is put in communication with line 812a, energizing the head end of motor 496a to raise the yoke 498a and rolls 499a. When rolls 499a reach the desired position, solenoid C is de-energized and the lines are again blocked.

The function of one-way check valve 823a is the same as that of one-way check valves 813a and 817a, i.e., it prevents bleeding off of the system either due to internal leakage in valve 825a or if for one reason or another pump P₄ is shut down or its capacity is being absorbed somewhere else in the system.

Considering now the right-hand side of FIGURE 30, it will be seen that pump P₄ is through line 801a in communication with line 831a containing one-way check valve 833a and in turn also in communication with the four-way, three-position, solenoid-operated valve 835a.

Pump P₅, which develops 100 p.s.i. maximum, is also in communication with valve 835a through lines 837a and 839a. Line 837a also is in communication with a check valve 841a in line 843a, which is connected to a spring-biased, solenoid reversed, two-position valve 845a. Valve 845a is connected to lines 847a and 849a which are in turn in communication with the rod ends and head ends of the straightening roll cylinders 452a, respectively.

High pressure line 812a is also in communication with line 843a through check valve 852a and line 853a and is provided with pressure switch PR which in turn is electrically connected in a manner well-known in the art to the solenoid of unload control valve 807a.

Preferably, line 849a is provided with manually operable valves 850a adjacent the head ends of the clamping roll cylinders 452a.

It will be seen then that when valve 845a is in its solenoid de-energized position, as shown in FIGURE 30, the normal flow from pump P₅ is through line 805a, line 837a, one-way check valve 841a, line 843a to valve 845a, thence through the valve to line 847a and to the rod ends of the cylinders 452a to retract the clamping rollers 462a connected to piston rods 457a. At the same time, the head ends of these cylinders 452a are exhausting through valves 850a, normally open line 849a and valve 845a to the reservoir R.

When it is desired to clamp the end of a workpiece, the solenoid of valve 845a is energized, the valve then acting to place line 843a in communication with line 849a, valves 850a and the head ends of the cylinders 452a, thus forcing these rolls to clamp the plate against the previously described clamping rolls 490a (FIGURES 21 and 27). Meanwhile, the rod ends of the clamping roll cylinders 452a are exhausting through the line 847a and valve 845a to reservoir R. The piston rods 457a then move the depending rollers 462a against the top surface of the workpiece to flatten its ends against the bottom rolls 490a.

To release the workpiece, the valve 845a is de-energized. This allows the valve-to-valve placing line 849a to be put in communication with the reservoir R, thus exhausting the head end of the hold-down cylinders 452a while line 847a is placed in communication with line 837a to pressurize the rod ends of the cylinders 452a and raise the rollers 462a. It will be noted that check valve 841a serves to block line 837a to prevent the rollers from creeping down, as would be the case were the system de-energized.

Since initial movement and retraction of the hold-down cylinders is through pump P₅ of high volume low pressure output, it will be seen that these rollers 462a will be actuated fairly rapidly but with comparatively little force. However, in the case of the hold-down rolls, it has been found that a greater force than that which can be developed in cylinders 452a by pump P₅ is often required to flatten the end of thicker plates to get them into the gripping jaws. To this end, high pressure line 812a carrying the high pressure low volume output of pump P₄ is connected to line 843a through one-way check valve 852a and line 853a. It suffices to say presently that the lines 847a, 849a, valve 845a and hold-down cylinders 452a are designed to withstand the high pressure output of pump P₄. Thus, if valve 852a is set to open only when the high pressure in line 812a exceeds a predetermined value, then the valve 845a, etc., will be subject to high pressure only at desired times, as will be apparent.

Referring now to the gripping jaw system, it will be seen that valve 835a which controls the jaw mechanisms is a three-position, solenoid-operated, spring-centered valve. Lines 831a and 839a are in communication with this valve as are lines 855a and 851a. Line 839a is in communication with the low pressure, high volume pump P₅, while line 831a is in communication with high pressure line 812a through high pressure relief valve 810a and one-way check valve 833a. Line 855a is in communication with the rod ends of the jaw actuating cylinders 124a, 124b in the upper and lower manifold housings 122a, 122b through line 859a. Line 851a is in communication with the head ends of these same cylinders through line 861a. In addition, line 851a is in direct communication with an intensifier 860a.

The intensifier 860a is a simple cylinder and piston-type device. The piston 863a thereof is provided with a rod 865a which in effect reduces the working area of the one side of the piston. In this case, the ratio between the head side and rod side of piston 863a is three to one; that is, there is a three-times greater working area

on the head side of piston 863a as there is on the rod side.

The head end of the intensifier 860a is connected to line 851a. The rod end, however, is in communication with the strut cylinders 198a, 198b, previously described in connection with FIGURE 24. Line 855a is also in communication with these cylinders through a one-way check valve 867a. In addition, line 861a, the head end line, is in communication with low pressure line 837a through a pilot-operated, one-way check valve 870a which is responsive to the pressure in line 859a.

Considering now the operation of the gripping jaw cylinders 124a, 124b, it will be assumed that an initial start-up is being made, valve 835a being in a centered position, as shown in FIGURE 30, with all ports blocked. Solenoid F is energized and valve 835a responds, placing line 831a in communication with lines 851a and 861a and line 839a in communication with lines 855a and 859a. Fluid from low pressure pump P₅ will then flow from lines 837a, 839a through the valve 835a to line 855a and one-way check valve 867a into the strut cylinders 198a and 198b. Low pressure fluid will also flow through line 859a to the rod end of the cylinders 124a, 124b. High pressure fluid, meanwhile, is flowing through valve 833a, line 831a and valve 835a into intensifier 860a. Also, high pressure fluid flows through line 861a to the head ends of the manifold housings 122a, 122b. For a brief moment, since the volume of high pressure fluid exceeds that of the low pressure fluid, the only effect on the system is the filling of the strut cylinders 198a and 198b. However, as the high pressure side begins to act, it will be seen that check valve 867a closes and intensifier 860a, now full of oil, will act to compress the fluid trapped in line 864a and strut cylinders 198a and 198b. High pressure also begins to act on the head ends of the cylinders 124a, 124b and, because of the differential in pressure, the pistons 130a, 130b (FIGURE 24) will move in these cylinders to close the jaws 110a, 110b (FIGURE 24). Since the oil-filled strut cylinders act as rigid members, they will be pulled by the movement of the gripping jaw moving shafts 192a, 192b. Since these shafts are geared together by segments 194a, 194b, all the jaws will close on the end of the workpiece.

In the meanwhile, referring again to FIGURE 30, the hold-down cylinders will have flattened the plate, assuring equal gripping action of both upper and lower jaws 110a, 110b.

The entire system remains energized as the previously described stretching cycle is carried out. After stretching, it will then be necessary to release the workpiece. To accomplish this, solenoid E of valve 835a is energized and solenoid R" is de-energized. Valve 835a then reverses, bringing line 839a into communication with line 851a and line 831a into communication with line 861a. At the same time, the high pressure fluid from pump P₄ then passes from line 831a through valve 835a to line 855a and check valve 867a. Since check valve 867a will not open, the fluid then passes through line 859a to the rod ends of the cylinders 124a, 124b.

In the meantime, low pressure line 837a has been put in communication with the head end of intensifier 860a and through the line 861a with the head ends of the cylinders 124a, 124b. Since the line 855a and strut cylinders 198a, 198b are filled and constitute a closed system when low pressure is applied to the intensifier 860a, the pressure in the strut cylinders 198a, 198b drops until the pressure forces piston 863a to the head end of the cylinder. Meanwhile, high pressure through line 859a acting on the rod ends of pistons 130a, 130b in cylinders 124a, 124b has begun to move these pistons against the low pressure of line 861a to the head ends of cylinders 124a, 124b to pull the jaws 110a, 110b from the workpiece. As the pressure builds up in line 859a, however, the pilot-operated check valve 870a

opens, placing the line 861a of the system in communication with relief valve 806a which unloads the system to reservoir R.

It will be noted that relief valve 806a is only closed under two conditions. One condition exists when the pressure acting on pressure switch PR in line 843a closes its control 807a due to a preselected minimum in line 843a, and the other is when valve 835a is in clamp position so as to prevent slamming of the jaws as they clamp on a workpiece.

With the unclamping, complete valve 835a is de-energized completely blocking all lines to hold the jaws 110a, 110b in retracted position.

It will be appreciated that, while only one set of clamping or hold-down roll cylinders and jaw-operating mechanisms is shown, the controlling circuits for these mechanisms are duplicated for both gripping head assemblies 100a and 200a.

One additional feature of the gripping jaw operation warrants consideration and this in connection with FIGURES 22 and 24. It will be seen that the fluid which enters a chamber 125a is a high pressure fluid. Piston 152a, therefore, is biased toward this chamber with sufficient pressure to withstand the normal operating pressure developed in chamber 125a. Similarly, the valve body 162a is biased against its set with equal pressure.

When a workpiece breaks, however, the jaws 110a, 110b tend to fly back. While some of the energy is dissipated in movement of the gripping heads 100a, 200a, because of the initial inertia, this action is not immediate and the jaws would thus take all the initial shock. However, in the present apparatus, some of the energy is absorbed by movement of the gripping jaws 110a, 110b. This action occurs as the jaws are driven toward a released position by the sudden reversal of shock loads lifting poppet valve 172a from its seat. Fluid then passes from a chamber 125a through ports 166a and acts to drive piston 152a toward the upper end of cylinder 126a. Some fluid will also be forced through restricted orifice 180a. The strut cylinders 198a, 198b also telescope very slightly because the fluid therein is slightly compressible and the jaws move toward a released position, the workpiece actually sliding toward the open rear of the slot S₄. By the time a piston 130a reaches the end of its rearward travel, the movement of the gripping heads has begun and the shock loads decrease. Fluid forced into a cylinder 126a then pushes poppet valve 172a against seat 170a and bleeds through aperture 176a allowing piston 152a to return to its normal position. In addition, fluid again bleeds through orifice 180a until a condition of equilibrium is again established.

The movement of the gripping heads, of course, actuates the hydraulic snubbers and, in addition, actuates the relief valves 550a and 540a included in the main hydraulic circuit, shown in FIGURE 29, to permit the system to react to the shock loads.

From the above description, it may be seen that the instant invention represents a new and novel development in the art of stretching large workpieces. Equally obvious is the fact that various changes and modifications may be made therein which are within the spirit and scope of the principles disclosed and the invention is limited only to the extent as defined in the appended claims, wherein:

What is claimed is:

1. An apparatus for elongating workpieces comprising in combination a spaced, mutually opposed pair of workpiece gripping head assemblies, tube-like means interposed between said gripping head assemblies for moving one of said head assemblies with respect to the other and effecting tensile elongation of a workpiece interposed therebetween, said tube-like means having a manipulating cylinder means disposed therein for moving the said one of said gripping head assemblies relative to the other, and stretching cylinder means associated

with said tube-like means for continuing the movement of the said one of the gripping head assemblies after the initial movement thereof by said manipulating cylinder means has introduced an initial stress in a workpiece, both said manipulating and said stretching cylinder means then acting in concert to elongate a workpiece.

2. A workpiece elongating apparatus as defined in claim 1 including a valve means and means connecting said valve means to said manipulating and stretching cylinder means, said valve means being operable to produce sequential operation first of said manipulating cylinder means and then of said stretching cylinder means.

3. An apparatus for elongating workpieces including a pair of relatively moveable workpiece gripping assemblies, one of which is adjustably fixed with respect to the other during operation of the apparatus to elongate a workpiece and the other of which is moveable during elongation of a workpiece, tube-like means interposed between said workpiece gripping assemblies for connecting and moving the said moveable gripping assembly during elongation of a workpiece with respect to the adjustably fixed workpiece gripping assembly, said tube-like means including a plurality of pairs of hydraulically actuated cylinder means, valve means for controlling the operation of said pairs of cylinder means, said valve means acting to cause one pair of said cylinder means to operate to move said last-mentioned gripping assembly and then operation of another pair of cylinder means whereby the respective pairs of cylinder means act first sequentially and then in concert to elongate a workpiece.

4. An apparatus as defined in claim 3 wherein said second acting pair of said pairs of cylinder means is of larger size than said first acting pair of said pairs of cylinder means.

5. In a stretching apparatus for elongating workpieces, a pair of workpiece gripping assemblies, each of said gripping assemblies comprising a pair of elongated anchor beams so spaced and disposed with respect to each other as to define an open-backed elongated slot therebetween, a line of individual jaw elements carried by each beam and disposed adjacent the slot defined therebetween for gripping a workpiece the jaw elements in one line being arranged and aligned with the jaw elements in the other line to provide a plurality of pairs of cooperating opposed jaw elements, said jaw elements being individually releaseable upon failure of a workpiece during elongation whereby said workpiece may move relative to a gripping assembly and through said slot and fluid actuated means for both actuating said jaw elements and for absorbing the shocks imposed on said jaw elements upon the failure of the workpiece engaged by said jaw elements.

6. A stretcher mechanism for elongating workpieces by a tensile pull thereon, said stretcher mechanism comprising a pair of oppositely disposed relatively moveable workpiece gripping assemblies, tube-like means provided with a plurality of pairs of piston and cylinder assemblies disposed between and interconnecting said workpiece gripping assemblies, said piston and cylinder assemblies being adapted upon the actuation thereof to move said gripping assemblies apart one with respect to the other, a hydraulic system for supplying fluid pressure to said pairs of piston and cylinder assemblies and means including pilot-operated sequence valve means in said hydraulic system for effecting expansion of one pair of piston and cylinder assemblies prior to expansion of the other pair of piston and cylinder assemblies, said sequence valve means being operated in response to pressure developed in said first pair of piston and cylinder assemblies during the expansion thereof.

7. An apparatus for stretching workpieces comprising a pair of tube-like connecting assemblies disposed

in spaced and parallel relationship to each other, support means engaging the ends of the tube-like connecting assemblies and maintaining said tube-like connecting assemblies in spaced, parallel, but freely moveable relation axially of their length, a pair of workpiece gripping assemblies adjustably fixed to said tube-like connection assemblies, piston and cylinder means disposed in each of said tube-like connecting assemblies and acting upon said gripping assemblies and through said tube-like connecting assemblies to move one of said workpiece gripping assemblies away from said other gripping assembly whereby a workpiece gripped by said gripping assemblies will be elongated, and means for rendering said other gripping assembly immobile during the movement of said one gripping assembly away therefrom.

8. An apparatus as defined in claim 7 wherein the piston and cylinder means acting upon said gripping assemblies comprises a plurality of pairs of sequentially actuated hydraulic piston and cylinder means of varied diameters disposed in back-to-back relationship.

9. An apparatus as defined in claim 7 including shock absorber means connected to an end of each of said tube-like connecting assemblies, said shock absorber means including a fixed cylinder charged with a compressible gas, a piston slidable in said cylinder and biased toward one end thereof by said gas.

10. An apparatus as defined in claim 8 wherein said plurality of pairs of piston and cylinder means are actuated by a hydraulic system, said system including a pair of pressure sensitive pilot-operated sequence valves interposed in said system to act between each pair of said plurality of pairs of piston and cylinder means whereby sequential actuation of said plurality of pairs of piston and cylinder means is effected.

11. An apparatus as defined in claim 10 wherein said pilot-operated valves are housed within said tube-like connecting assemblies.

12. An apparatus as defined in claim 7 including cable and drum means connected to said moveable workpiece gripping assembly for preventing offsetting of one side of the moveable workpiece gripping assembly with respect to the other side thereof as the moveable workpiece gripping assembly is moved during the elongation of a workpiece, said cable means also being tensioned about said drum means.

13. In an apparatus for elongating a workpiece and the like, means for actuating said apparatus, said means including a first cylinder and piston means and a second cylinder and piston means, said first and second-mentioned piston and cylinder means being disposed in back-to-back relationship, said first cylinder and piston means being actuated subsequent to and in concert with said second-mentioned piston and cylinder means, hydraulic circuit means for actuating both of said cylinder and piston means, said circuit means including a source of pressure and a pressure sensitive valve means actuated in response to pressure in said second-mentioned cylinder and piston means to admit pressure to said first-mentioned cylinder and piston means, said valve means comprising a cylindrical housing, a ported spool disposed within said housing, a pilot piston carried within a pilot cylinder and connected to said ported spool, means for placing said pilot piston and said second-mentioned cylinder and piston means in communication whereby the pressure in said second-mentioned piston and cylinder means may operate said pilot piston upon reaching a predetermined pressure, said pilot piston moving said ported spool within said housing, said housing including port means adapted to communicate with said ported spool when said ported spool has been actuated by said pilot piston whereby fluid pressure from said second-mentioned cylinder and piston means may enter said first-mentioned cylinder and piston means and then both of said piston and cylinder means can act in concert to elongate a workpiece.

14. An apparatus for elongating a workpiece as defined in claim 13 wherein said valve means is carried by said second-mentioned piston means while being disposed within said second-mentioned cylinder means.

15. An apparatus for elongating workpieces as defined in claim 13 wherein said valve means further includes biasing means including a spring acting against said spool whereby pressure generated in said first-mentioned piston and cylinder means may be exhausted through said valve means against the bias of said spring.

16. In an apparatus for stretching workpieces, said apparatus comprising a pair of tubular connecting assemblies, a pair of workpiece gripping assemblies adjustably connected to said tubular connecting assemblies, a pair of sequentially operated hydraulic pistons and cylinders housed within said tubular connecting assemblies for acting through said tubular connecting assemblies upon said workpiece gripping assemblies, a sequence valve for sequentially actuating the hydraulic pistons and cylinders in said pair of hydraulic pistons and cylinders, said sequence valve including a cylindrical housing having a plurality of spaced and radially disposed ports in the wall thereof, one of said radial ports being in communication with a longitudinal passage disposed within said wall, a valve spool disposed in said housing and moveable axially thereof, said spool including a skirted portion having a port adapted to register selectively with one or the other of said radial ports and when in intermediate position to block both of said ports, means connected to said valve spool and responsive to the pressure in said first-mentioned radial port for moving said spool to a position where said first-mentioned radial port and the port in said spool skirt are in communication with one another, said means comprising a pilot piston, a pilot cylinder surrounding said piston, one end of said cylinder also being in communication with said first-mentioned radial port, a check valve subject to pressure in said first-mentioned radial port and openable at a predetermined pressure to cause movement of said pilot piston and said valve spool in one direction, said pilot piston and said valve spool remaining stationary with respect to said first-mentioned radial port and said port in said skirt in communication therewith after pressure is removed from said first-mentioned radial port, a further normally closed check valve in communication with said first-mentioned radial port, said last-mentioned valve being subject to additional closing bias by pressure in said first-mentioned radial port.

17. A valve for a workpiece stretching apparatus as defined in claim 16 wherein the said pilot piston includes a pilot rod connected to said valve spool, the ratio of the areas of the head side and rod side of said pilot piston being two to one whereby said pilot piston remains immobile when pressure is applied to its rod side, until the pressure is relieved on its head side by opening of said second-mentioned check valve.

18. In an apparatus for stretching workpieces which includes two workpiece gripping assemblies interconnected at each side by pairs of hydraulic cylinder means acting to move one of said assemblies relative to the other, means for actuating said pairs of hydraulic cylinder means, said actuating means including a hydraulic system provided with a source of pressure and separate input lines in communication with the said pairs of cylinder means, means acting to balance the input to each of said pairs of cylinder means including valve means disposed in each of said input lines, means connecting said valve means to a common differential mechanism, said differential mechanism including input shafts, drums and cables on said drums connected to opposite sides of the movable one of said pair of workpiece gripping assemblies, said drums being fixedly positioned with respect to said assembly whereby movement thereof causes reeling and unreeling of said cables on said drums and rotation of said input shafts, said differential mechanism acting in response to a difference of rotational speed of said input shafts

due to unequal movement of the opposite sides of said moveable workpiece gripping assembly to operate said valve means whereby the inlet pressure to said pairs of cylinder means at the opposite sides of said moveable workpiece gripping assembly will be varied to restore equalized movement of said opposite sides of said moveable workpiece gripping assembly.

19. An apparatus for stretching plates comprising a pair of workpiece gripping assemblies, means supporting each of said assemblies for movement transversely of their length, said assemblies including a pair of inwardly tipped upper and lower beam members, a pair of opposed gripping jaw-carrying faces defined between said members and forming a generally divergent slot, a plurality of individual gripping jaws mounted in a line on each of said faces and moveable therealong the jaws in one line being arranged and aligned with the jaws in the other line to provide a plurality of pairs of cooperating opposed jaws, means for moving said jaws, said means comprising fluid motor means connected to each of said jaws, a shaft means, means connecting said shaft means to each of said jaws such that all of said jaws are moveable simultaneously toward and from a workpiece passed through said slot.

20. An apparatus for stretching metal plate comprising a pair of plate-gripping assemblies moveable transversely of their length along a fixed path, means supporting each of said plate-gripping assemblies in moveable relation one with respect to the other, tube-like connecting means interposed between and connecting said plate-gripping assemblies together, said connecting means also being provided with a first pair of piston and cylinder means and a second pair of piston and cylinder means disposed in back-to-back relationship with respect to said first-mentioned piston and cylinder means, means including a sequence valve disposed in said tube-like connecting means for controlling the operation of said pairs of piston and cylinder means in such a fashion that said second-mentioned pair of piston and cylinder means is actuated only after a predetermined force is exerted by said first-mentioned piston and cylinder means, said tube-like connecting means further including means on the outer surface thereof which is releasably engageable with means carried by said plate-gripping assemblies so that each of said gripping assemblies may be adjustably locked to said tube-like connecting means.

21. An apparatus as defined in claim 20 wherein said releasably engageable means for locking the gripping assemblies to the tube-like connecting means is comprised of a series of circumferentially spaced rib sections provided on an external surface of the tube-like connecting means, said rib sections being interdigitated with circumferentially spaced, smooth outer surface portions on the tube-like connecting means and wherein each of said gripping assemblies includes a pair of similarly configured lock rings moveable into and out of engagement with said rib sections on the tube-like connecting means.

22. In an apparatus for elongating workpieces, a pair of gripping head assemblies, tube-like means interconnecting said gripping head assemblies together, said tube-like means also including piston and cylinder means for acting through said tube-like means and for moving one of said gripping head assemblies with respect to the other during the elongating of a workpiece, each of said assemblies comprising upper and lower beam members, means for gripping a workpiece mounted on said beam members, means disposed in front of said gripping means to engage and flatten the end of a workpiece prior to insertion thereof between and the engagement thereof by said gripping means, whereby the workpiece will be substantially aligned with a plane extending medially through a slot provided between the upper and lower beam members of a workpiece gripping head assembly, said second-mentioned means comprising a lower series of rollers, a support for said rollers, said support including wedge-like cam surfaces, means on said lower beam member for

engaging said wedge-like surfaces on said support whereby said rollers may be raised up and down at the will of an operator, an upper series of rollers, fluid motor means connected to said upper series of rollers whereby a workpiece resting on said lower series of rollers may be engaged between the upper and lower series of rollers and compressed by action of said fluid motor means to flatten the end thereof, a common fluid circuit means for said piston and cylinder means and said fluid motor means, and means in said fluid circuit means for synchronizing the operation of said fluid motor means with the operation of said piston and cylinder means.

23. An apparatus for elongating workpieces comprised of a pair of workpiece gripping assemblies, means for moveably supporting each of said workpiece gripping assemblies and guiding said workpiece gripping assemblies in an axial direction transverse of their length, means interposed between the workpiece gripping assemblies for moving one of said gripping assemblies relative to the other, a drawbar disposed below and extending between each of said gripping assemblies, means carried by each of said gripping assemblies and for moveably engaging said drawbar, said means being releasably connected to said drawbar at the will of an operator, and said drawbar engaging means acting in conjunction with said moving means for changing the relative position of one workpiece gripping assembly relative to the other in order that the area between said workpiece gripping assemblies may be varied to accommodate workpieces of varying lengths.

24. An apparatus as defined in claim 23 wherein said workpiece gripping assemblies are provided with wheeled trucks engageable with spaced pairs of rails which extend in the same direction as the normal directional movement of each of said workpiece gripping assemblies with a drawbar lying between and paralleling a pair of rails.

25. An apparatus for elongating workpieces including a pair of workpiece gripping assemblies one of which is adjustably fixed with respect to the other during operation of the apparatus to elongate a workpiece and the other of which is moveable during elongation of the workpiece, each of said assemblies including a pair of elongated upper and lower beam members, a pair of opposed gripping jaw-carrying faces defined between said members and forming a generally divergent elongated slot, a plurality of gripping jaws mounted in a line on each of said faces and moveable therealong toward and away from one another the jaws in one line being arranged and aligned with the jaws in the other line to provide a plurality of pairs of cooperating opposed jaws, means for moving said jaws, said means comprising fluid motor means connected to each of said jaws, a shaft means, means connecting said shaft means to each of said jaws such that all of said jaws are moveable simultaneously toward and away from a workpiece passed through said slot, and means interposed between said workpiece gripping assemblies for moving said moveable gripping assembly during elongation of a workpiece.

26. An apparatus as set forth in claim 25 wherein said beams are so spaced and disposed with respect to each other that the said divergent slot disposed therebetween is open-backed.

27. In an apparatus for stretching workpieces which includes two workpiece gripping assemblies interconnected at each side by pairs of fluid-operated means acting to move one of said assemblies relative to the other, a pair of elongated tube-like assemblies interconnecting said workpiece gripping assemblies and housing said fluid-operated means, said fluid-operated means including a first cylinder and piston means and a second cylinder and piston means, said first and second-mentioned piston and cylinder means being disposed in back-to-back relationship, said first cylinder and piston means being actuated subsequent to and in concert with said second cylinder

and piston means, fluid circuit means for actuating both of said cylinder and piston means, said circuit means including a source of fluid pressure and a pressure sensitive valve means actuated in response to pressure in said second cylinder and piston means to admit pressure to said first cylinder and piston means, said valve means comprising a cylindrical housing, a ported spool disposed within said housing, a pilot piston carried within a pilot cylinder and connected to said ported spool, means for placing said pilot piston and said second cylinder and piston means in communication whereby the pressure in said second piston and cylinder means may operate said pilot piston upon reaching a predetermined pressure, said pilot piston moving said ported spool within said housing, said housing including port means adapted to communicate with said ported spool when said ported spool has been actuated by said pilot piston whereby fluid pressure from said second cylinder and piston means may enter said first cylinder and piston means and then both of said cylinder and piston means can act in concert to elongate a workpiece.

28. In a stretching apparatus for elongating workpieces, at least one workpiece gripping assembly, said gripping assembly comprising a pair of elongated anchor beams so spaced and disposed with respect to each other as to define an open-backed elongated slot therebetween, means carried by a beam and disposed adjacent the slot defined therebetween for gripping a workpiece, said means comprising a plurality of individual and aligned jaw elements mounted in a line on each of said surfaces the jaw elements in one line being arranged and aligned with the jaw elements in the other line to provide a plurality of pairs of cooperating opposed jaw elements, said jaw elements being releasable upon failure of a workpiece during elongation whereby said workpiece may move relative to the gripping assembly and through said slot.

29. An apparatus for stretching plates comprising at least one workpiece gripping assembly, said assembly including a pair of elongated upper and lower beam members, a pair of opposed gripping jaw-carrying faces defined between said members and forming a generally divergent elongated slot, a plurality of gripping jaws mounted in a line on each of said faces and movable therealong the jaws in one line being arranged and aligned with the jaws in the other line to provide a plurality of pairs of cooperating opposed jaws, means for moving said jaws, said means comprising fluid motor means connected to each of said jaws, a shaft means, means connecting said shaft means to each of said jaws such that all of said jaws on each of the faces of said jaw-carrying faces are movable simultaneously toward and from a workpiece passed through said slot.

30. An apparatus for stretching plates comprising a pair of workpiece gripping assemblies, means for supporting each of said assemblies for movement transversely of their length, means interposed between said assemblies for moving one of said assemblies relative to the other, said last-mentioned means comprising a pair of parallel tube-like assemblies, each of which includes a movable sleeve portion, said pair of parallel tube-like assemblies connecting said workpiece gripping assemblies together and said sleeve portion being connected to one of said workpiece gripping assemblies and comprising a fluid cylinder, piston means disposed within said cylinder, means including a source of fluid for actuating said piston means so as to move said cylinder relative to said piston means whereby the one workpiece gripping assembly will be carried toward and away from the other of said workpiece gripping assemblies, means for rendering the other of said workpiece gripping assemblies immobile during the time said one workpiece gripping assembly is carried toward and away therefrom, a second cylinder interposed in one of the tube-like assemblies, said second-mentioned cylinder including a piston means contactable with that end of said sleeve portion disposed most closely adjacent

thereto and wherein said source of fluid comprises a means including a valve means responsive to pressure acting on said first-mentioned piston means in said first-mentioned cylinder whereby fluid from said source of fluid is admitted to said second-mentioned cylinder after a predetermined force has been exerted by said first-mentioned piston means and whereby the force developed by said second-mentioned piston means and cylinder supplements that developed by said first-mentioned piston means and cylinder upon contact of said second-mentioned piston means with the said sleeve portion to continue elongation of the workpiece beyond the capacity of the first-mentioned piston means and cylinder.

31. In an apparatus for elongating a workpiece the combination of a pair of gripping assemblies, a pair of tubular members connected to one of said gripping assemblies, means carried by said tubular members acting on the other of said gripping assemblies to move said last-mentioned assembly relative to said tubular members, said means comprising a piston and cylinder means housed within each of said tubular members, piston rod means having one end connected to said piston and cylinder means and telescopingly movable into and out of each of said tubular members and having its other end fixed to the other of said pair of gripping assemblies, a hydraulic system including a source of pressure and valve means for actuating said piston and cylinder means and said piston rod means, a second piston and cylinder means of large diameter, said second piston and cylinder means including cylinders supportingly carried by said last-mentioned gripping assembly, piston means disposed within said second cylinder means and carried by and slidably upon said piston rod means, said valve means including a pilot valve responsive to the pressure actuating said first-mentioned piston and cylinder means to admit fluid from said hydraulic system into said second cylinder means to cause said second piston means to slide axially of said piston rod means and engage the ends of said tubular members.

32. An apparatus for elongating a workpiece as defined in claim 31 wherein said piston rod means is hollow and wherein said valve means is carried by said first-mentioned piston and cylinder means and is actuated to permit fluid flow through said hollow piston rod means.

33. An apparatus as defined in claim 32 wherein said first-mentioned piston and cylinder means and said valve means are housed within said tubular members.

34. An apparatus as defined in claim 32 wherein said first-mentioned piston and cylinder means includes pressure relief means actuated by unbalanced pressure in said first-mentioned cylinder means produced by fracture of a workpiece during stretching to permit movement of a piston in said first-mentioned cylinder means.

35. In a stretching apparatus for elongating flat workpieces and including a pair of oppositely disposed relatively moveable gripping mechanisms and means for moving said mechanisms one with respect to the other whereby a workpiece gripped by said mechanisms can be elongated lengthwise, said means comprising a pair of tubular members having threaded exteriors, means fixing one of said gripping mechanisms to the threaded exteriors of said tubular members after said one of the gripping mechanisms has been moved to a predetermined position on said tubular members, means connecting the other of said gripping mechanisms to the said tubular members, said last-mentioned means including a first cylinder assembly mounted within a tubular member, a piston rod extending from said first cylinder assembly, a second cylinder assembly supportingly carried by and connected to the other of said gripping mechanisms, a first piston disposed within said first cylinder assembly and connected to said piston rod, a second piston carried by said piston rod, said second piston being slidably disposed on said rod and moveable

telescopically within the second cylinder assembly, a hydraulic circuit means for actuating said first and second cylinder assemblies, said hydraulic circuit means including a sequence valve means interposed in said hydraulic circuit means between said first and said second cylinder assemblies whereby said second cylinder assembly will not be actuated until said first-mentioned cylinder assembly has exerted a tensile pull on a workpiece interposed between said gripping mechanisms, said sequence valve means including a pilot valve sensitive to pressure developed in said hydraulic circuit means, whereby when pressure in said hydraulic circuit means reaches a predetermined point said pilot valve will operate said sequence valve means to actuate the piston that is telescopically moveable in said second cylinder assembly so as to continue elongation of said workpiece.

36. In an apparatus for elongating a workpiece comprising a first and second workpiece gripping assembly, means interposed between said assemblies for joining said assemblies together and for moving said workpiece gripping assemblies relative to each other, said interposed means including a pair of threaded tubular members, locking means on said first gripping head assembly engageable with said threaded tubular members, a drive mechanism operable to motivate said locking means and to move said first gripping head assembly to a predetermined fixed position on said tubular members and with said first gripping head assembly remaining in said predetermined fixed position during elongation of a workpiece, a first piston and cylinder means housed in said tubular members and a second piston and cylinder means connected to said second workpiece gripping assembly and said first piston and cylinder means, the cylinder of said second piston and cylinder means also being supportingly carried by said second workpiece gripping assembly and means for actuating all of said piston and cylinder means in unison so as to move said second workpiece gripping head assembly with respect to said first fixed workpiece gripping head assembly and effect elongation of a workpiece held therebetween.

37. An apparatus for stretching plates comprising a pair of workpiece gripping assemblies, means supporting each of said assemblies for movement transversely of their length, said assemblies including a pair of inwardly tipped upper and lower beam members, a pair of opposed gripping jaw-carrying faces defined between said members and forming a generally divergent slot, a plurality of individual gripping jaws mounted on each of said faces and movable therealong, means for moving said jaws, said means comprising fluid motor means connected to each of said jaws and a shaft means, means connecting said shaft means to each of said jaws such that all of said jaws are movable simultaneously toward and from a workpiece passed through said slot said last mentioned means including a telescopic strut, such strut being filled with fluid under pressure.

38. An apparatus for stretching plates comprising a pair of workpiece gripping assemblies, means supporting each of said assemblies for movement transversely of their length, said assemblies including a pair of inwardly tipped upper and lower beam members, a pair of opposed gripping jaw-carrying faces defined between said members and forming a generally divergent slot, a plurality of individual gripping jaws mounted on each of said faces and movable therealong, means for moving said jaws, said means comprising fluid motor means connected to each of said jaws and a shaft means, means connecting said shaft means to each of said jaws such that all of the jaws are movable simultaneously toward and from a workpiece passed through said slot, said fluid motor means being comprised of a first piston and cylinder means which receives fluid from a source of fluid pressure, a second piston and cylinder means in communication with said first piston

and cylinder means, valve means interposed between said first and second piston and cylinder means, said second-mentioned piston and cylinder means comprising a pneumatic-hydraulic shock absorber means adapted to absorb shock loads imposed on said gripping jaws due to failure 5 of a workpiece.
